MACHINE AND METHOD FOR USE IN MAKING RIBBED STRIPS FOR INSOLES

Alfred S. Clark, Beverly, Mass., assignor to United Shoe Machinery Corporation, Flemington, N. J., a corporation of New Jersey

Application July 18, 1947, Serial No. 761,890

87 Claims. (Cl. 154—1.8)

1

This invention relates to machines and methods for use in making composite ribbed strips for attachment to insoles to provide sewing ribs thereon and is illustrated herein with particular reference to the manufacture of ribbed strips of the type disclosed in United States Letters Patent No. 2,458,500, granted January 11, 1949 on an application filed in the names of Frederic E. Bertrand and Alfred S. Clark.

A ribbed strip of the type referred to, as disclosed in the above cited patent, comprises a composite strip composed of two strips of indefinite length folded in a manner to produce a four-ply rib having inner and outer flanges projecting laterally from opposite sides of the rib, the outer flange comprising a single layer of material and the inner flange comprising two plies, the upper layer of which extends inwardly a substantial distance beyond the lower layer to provide a wide reinforcement for the insole. The lower surfaces of the flanges, including the inwardly extending portion of the inner flange, are coated with pressure-responsive cement to adapt the strip for attachment by pressure alone to the outer surface of an insole which has been previously coated with pressure-responsive cement. As also disclosed in said patent, the four-ply rib may, if desired, be provided with stitches which extend widthwise through the rib adjacent to the base portion of the strip, the stitches preferably being chain stitches and, if desired, being composed of thread which contrasts in color with the material of the strips so that the stitches will be plainly visible in the completed strip to serve as a guide for the operator in making the shoe, for example, during the lasting and weltling or inseaming operations. Moreover, the rib of the composite strip is preferably inclined inwardly toward the inner flange at a substantial angle to the horizontal, this construction further facilitating the inseaming operation since it provides a definite groove or channel along the inner side of the rib for receiving the channel guide of the weltling machine.

An object of the present invention is to provide an improved machine for making composite ribbed strips of the type described above. Another object of the invention is to provide an improved method of making composite ribbed strips of that type in quantity production.

To these ends, and in accordance with its article aspect, the invention provides an improved machine having, in combination, mechanism for feeding strips of indefinite length in unison, a member for folding one of the strips

2

progressively during the feeding movement to form a two-ply layer, and means for thereafter folding another one of the strips progressively around the two-ply layer to cover a portion thereof and form a four-ply layer with remaining portions of the two-ply layer and other strip projecting beyond said four-ply layer, said last-named means being also arranged to bend said remaining portions laterally with respect to the four-ply layer to produce a composite strip having a four-ply rib with flanges projecting laterally from the base of the rib. As herein illustrated, the feeding mechanism operates continuously to move the strips progressively past the operating instrumentalities of the machine and the folding member folds one strip upon itself widthwise to form a two-ply layer while the other strip is maintained in a substantially flat position. Thereafter, the folded strip which, in the present construction, is the upper strip, is guided into engagement with the other, or lower, strip, after which the second folding means referred to operates progressively to fold the lower strip around the two-ply layer to form the four-ply layer. As the combined strips continue to travel through the machine, the folding means is provided with associated mechanism which operates progressively to bend the plies of the extending portion of the two-ply layer in opposite directions to position them at substantial angles to the four-ply layer, thereby producing a composite strip having a four-ply rib with inner and outer flanges projecting from its base, the inner flange, as herein illustrated, being covered by the remaining portion of said other, or lower strip, which extends a substantial distance beyond said flange to provide a wide reinforcement for the insole.

As illustrated, the ribbed strip after being formed is subjected to substantial pressure applied progressively during the feeding movement to shape the entire strip and also to press the rib firmly against the inner flange in order to flatten the strip temporarily and thereby facilitate winding the strip upon a spool or reel after it leaves the operating instrumentalities of the machine. The means for shaping and compressing the strip, as illustrated herein, comprises a pair of driven rolls shaped and arranged to impart a predetermined shape to the composite strip. Moreover, the rolls are also shaped to produce a crimp or crease in the upper portion of the multi-ply rib to provide a relatively narrow edge along the upper portion of the rib. Since the rib is pressed over against the inner

flange by said rolls, the rib will continue to lean toward said inner flange in the completed strip when the pressure is relieved. The rolls may be adjusted to apply substantial pressure to the composite strip and, since they are knurled to increase friction, they also operate as the feeding mechanism for moving the strips progressively through the machine.

In accordance with another feature of the invention, the present machine is provided with means for supplying the strips to the feeding mechanism in sufficient lengths to supply said feeding mechanism with the strips under relatively light tension irrespective of the rate of feed of the feeding mechanism. As herein illustrated, the strip supplying means comprises constantly operating mechanism, including a crank, constructed and arranged to pull a length of strip intermittently from a source of supply, such as a roll or reel, under substantial tension, the length of strip pulled from the reel each time being controlled by the length of the preceding feeding movement of the strip. Means is also provided to stop the machine automatically if for any reason the pull-off mechanism is unable to pull the strip from its reel, if, for example, the tension on the strip becomes so great that there is danger of tearing or breaking the strip or damaging the machine by continued operation of the mechanism.

The reels forming the source of supply are rotatably arranged adjacent to the pull-off mechanism. In order to prevent undue delays or stoppages in the operation of the machine, it is desirable, once the strips have been properly inserted or threaded through the various operating mechanisms of the machine, to prevent the strips from running out of these mechanisms and thus making it necessary to thread new strips through the machine. Accordingly, means is provided at the source of supply for stopping the machine before the strip on the reel or reels becomes completely used up, this means, as herein illustrated, being constructed and arranged to stop the machine automatically when the strip on either reel has diminished to leave only a predetermined amount as determined, for example, by the operator when setting up or adjusting the machine. A fresh roll of strip can then be quickly attached to the remaining portion of the first roll, for example, by splicing to permit the new strip to be threaded into the operating mechanisms of the machine by the feeding mechanism in the normal operation of the machine. In this way, delays or stoppages in the work due to the necessity of threading new strips through the machine are avoided.

In accordance with still another feature, the illustrated machine is provided with means for automatically winding the composite strip upon a reel after the strip has been completed. As herein illustrated, the winding means includes a reel and power-operated mechanism for rotating the reel to wind the strip automatically thereon, said mechanism being constructed and arranged to rotate the reel under sufficient tension to wind the strip thereon irrespective of the increase in size or diameter of the reel as the windings thereon multiply. Besides winding the strip on the reel, the winding mechanism is arranged to distribute the strip automatically over the reel in a manner to position the strip substantially evenly across the width of the reel. In addition, the winding mechanism is provided with further means for stopping the machine

automatically when the reel is full or, if preferred, when the windings upon the reel reach a predetermined size or diameter, this means, as herein illustrated, including a micro-switch and mechanism actuated by engagement with the strip on the reel for opening the switch and stopping the machine.

If desired, the present machine is also adapted to insert stitches in the composite ribbed strip, the stitches, as indicated above, being preferably located adjacent to the base of the rib and extending widthwise through the plies thereof. As illustrated, the stitches may be omitted, if desired, by merely disconnecting the stitching mechanism from the power-operated mechanism of the machine without affecting the operation of the rest of the machine. Moreover, means is provided, operating in conjunction with the stitching mechanism if used, for automatically stopping the machine if the thread should break, this means, as illustrated herein, including a micro-switch and mechanism controlled by the tension of the thread for opening the micro-switch if the thread breaks, thereby stopping the machine.

In its method aspect, the invention provides an improved method of making composite ribbed strips for insoles which includes the steps of feeding strips of indefinite length in unison in a predetermined path, folding one of the strips progressively during the feeding movement to form a two-ply layer, folding another strip progressively around the two-ply layer to cover a portion thereof and form a four-ply layer with the remaining portions of the two-ply layer and other strip projecting therefrom, and bending the remaining or projecting portions of said two-ply layer and other strip laterally into substantial angles relatively to the four-ply layer to form flanges at one end thereof, the bending operation, as herein illustrated, acting to turn the two plies of the remaining portion of the two-ply layer in opposite directions, thereby forming inner and outer flanges on the four-ply layer or rib, one of said flanges, the inner flange as herein illustrated, being covered by the remaining portion of said other layer which extends a substantial distance beyond said flange to provide a wide reinforcement for the insole.

The method further includes the step of temporarily compressing or flattening the composite strip to cause the rib to be inclined inwardly toward the inner flange in the finished strip, thereby permitting the strip to be readily wound upon a reel. It further contemplates inserting stitches through the ribbed strip, if desired, although the stitches may be omitted without weakening or otherwise affecting the strip since coatings of pressure-responsive cement on the strips insure that the composite strip will be strongly constructed. In addition, the present method includes the step of supplying the precoated strips under relatively light tension for use in forming the composite strip, and for supplying the strips in sufficient lengths to carry out the method irrespective of the speed at which the strips are fed. Moreover, as a final step, the method includes the operation of winding the composite strip automatically upon a reel, the winding being performed in such a manner that the strip will be wound upon the reel under sufficient tension to hold the strip properly on the reel whether the reel is empty or nearly full, and also in a manner which insures that the completed strip will be

distributed substantially evenly across the width of the reel.

With the above and other features and aspects in view, the invention will now be described in detail in connection with the accompanying drawings and will thereafter be pointed out in the claims. In the drawings,

Fig. 36 is a fragmentary detail view of means on the winding mechanism for automatically stopping the mechanism when the reel is full.

The illustrated machine for making ribbed strips for attachment to welt insoles is adapted to operate upon a pair of relatively narrow strips A and B of indefinite length composed of textile or fabric material, such as canvas or Gem duck, the strips being preferably delivered in unison to the operating instrumentalities of the machine under relatively light tension and in superimposed relation to each other from a source of supply such as illustrated in Fig. 1. The strips A and B are preferably supplied to the operating instrumentalities from rolls 40, 42 of the strips wound respectively on fiber spools or reels 44, 46 carried by filler rolls 47 rotatably mounted by annular slot and screw arrangements on a shaft 48 secured in the upper end of a standard 50 on a bracket 52 fastened to a base 54 which supports the machine. In order to prevent the reels 44, 46 from turning loosely on the shaft 48, compression springs 56 are interposed between the reels and collars 58, 60 secured respectively to the opposite ends of the shaft by thumb-screws 62, thereby creating enough friction to prevent the reels from turning until sufficient tension is applied to the strips to overcome the force of the springs.

The upper strip A is coated on both surfaces with pressure-responsive cement, while the lower strip B is coated on one side only with such cement, the coated surface of the strip B facing upwardly toward the strip A, as viewed in Fig. 1.

The cement utilized in making the composite ribbed strip of the present invention is preferably neoprene cement although it could be latex or other pressure-responsive cement comprising synthetic materials which will not cause adhesion between two surfaces unless both are coated with the cement in which case a substantially permanent bond will be obtained upon the application of sufficient pressure.

In accordance with the present invention, the strips A and B are supplied from the rolls 40, 42 to the strip forming mechanisms of the machine under relatively light tension and are fed progressively through the machine during the strip forming operations. Since the lower strip B is 75 coated with pressure-responsive cement on its

upper surface only, the windings of the strip forming the roll 42 on the reel 46 are not stuck firmly together and the strip may be unwound from its roll by a fairly light pull sufficient merely to overcome the tension of the spring 56. Consequently, the lower strip B may be pulled directly from its roll and advanced through the machine by the strip feeding mechanism of the machine as will be explained hereinafter. The upper strip A, however, having pressure-responsive cement on both surfaces thereof, may have its windings stuck together by a fairly strong bond so that, in some cases at least, considerable force may be required to pull the strip from its roll. Accordingly, the strip A is unreeled or pulled from its roll by pull-off mechanism forming a part of the machine and adapted to provide a sufficient length of strip under relatively light tension to supply the strip feeding mechanism irrespective of the rate of feed of said feeding mechanism.

The pull-off mechanism of the machine, as illustrated in Figs. 1 to 4, inclusive, comprises a bracket 64 mounted on the base 54 and provided with an upstanding plate 66 upon the forward surface of which is rotatably mounted on stud screws a pair of spaced rolls 68 and 70, the rolls having peripheral flanges for holding the strip thereon and being arranged in substantially parallel relation. Located forwardly of the plate 66, above and approximately centrally of the spaced rolls 68 and 70, is an eccentric or crank in the form of a roll 72 rotatable about a pin 73 mounted eccentrically on the forward end of a shaft 74, the shaft having bearings in the plate 66 and in an upstanding projection 76 (Fig. 3) on the bracket 64 and being held against axial movement in the bearings by collars 78 and 80 pinned to the shaft. At its rearward end the shaft 74 has a pulley 82 pinned thereon and connected by a belt 84 to the power driving mechanism of the machine, as will be later explained, to rotate the shaft 74 in a counter-clockwise direction, as viewed in Fig. 1, and thereby cause the crank 72 intermittently to engage the length of the strip A which extends across the parallel rolls 68 and 70 in a relatively straight condition, as shown in Figs. 1 and 2, the crank depressing the strip upon each revolution and pulling a predetermined amount of the strip A from its roll 40 on the reel 44. If, during the normal operation of the machine, the feeding mechanism uses up the full amount of excess strip pulled from the roll 40 by the crank 72, the strip extending between the spaced rolls will be returned each time to the straight position illustrated in Fig. 1. If, however, the feeding mechanism does not use up the full amount of strip pulled from the roll, the length of strip extending between the spaced rolls 68, 70 will not be returned to a straight or taut position and, on its next rotation, the crank will merely pull off an additional amount of strip sufficient to permit the crank to assume its lowermost position. In other words, the arrangement is such that the pull-off mechanism will pull a length of strip A from its roll which is controlled by the length of the previous feeding movement of the strip through the machine, the full throw of the crank, of course, being great enough to provide sufficient excess strip to supply the feeding mechanism continuously even though the latter is operating at a high speed.

In order to prevent reverse or retrograde movement of the strip due to backlash in the mechanism or to rebounding of the roll 40 under

the tension created by the double-coated strip A, the pull-off mechanism is provided with means in the form of pawls which prevent any reverse movement of the strip A after it has once been pulled from the roll. As shown in Figs. 1 and 2, the strip A passes downwardly from its roll through a guide 85 and around an idler roll 86 rotatably mounted on a screw in the plate 66 and then passes forwardly or toward the left over the spaced rolls 68 and 70. From the roll 70 the strip A travels downwardly over another roll 88 which, under normal conditions, operates as a fixed idler roll but is rotatable on a pin 91 mounted in the forward end of an arm or lever 90 pivoted on a pin 92 in the plate 66 for a purpose that will be presently explained. The strip then passes upwardly over another idler roll 94 rotatable on a pin 96 mounted in the upper end of a bracket 98 fastened to the base 54 by screws 100, the strip thereafter moving forwardly or toward the left, as viewed in Figs. 1 and 3, into the ribbed strip forming instrumentalities of the machine.

Pivoted on the plate 66, below the roll 86, on a pin 102 is an upwardly extending pawl 104 (Figs. 1 and 2) which is urged toward the right about its pivot by a tension spring 106 extending between the pawl and a pin 108 on an upstanding arm 110 provided on the bracket 52. The pawl 104 engages the strip A under the idler roll 86 and grips the strip to prevent any reverse movement thereof while permitting the strip to pass freely around the roll during the normal feeding movement of the strip toward the left, as viewed in Fig. 1. The pawl 104, as illustrated, is maintained constantly in engagement with the strip by the spring 106.

Pivoted on a screw 112, above the spaced roll 70, is another pawl 114, the lower end of which engages the strip A as it passes over the roll 70, the pawl being arranged to grip the strip and prevent retrograde movement thereof but permitting free passage of the strip around the roll in the direction of the feeding movement of the strip. The pawl 114 is urged into engagement with a strip by a spring 116 extending between the pawl and a pin 118 on the plate 66. Pivoted beside the pawl 114 on a screw 120 is a lever 122, the lower portion of which is held against a cam 123 formed on the shaft 74 just rearwardly of the crank 72, the lever being maintained against the cam 123 by a spring 124 extending between the lever and a pin 126 on the plate 66. A screw 128 threaded through the pawl 114 engages the lever 122, the screw being positioned so that the lower end of the pawl will normally be located in operative engagement with the strip A. The pawl 114 is thus removed from engagement with the strip A intermittently upon each rotation of the cam 123 through the lever 122 and screw 128. Consequently, the pawl 114 is moved alternately into, and out of, engagement with the strip as it passes over the roll 70, the arrangement being such that the pawl engages the strip to prevent retrograde movement during the period that the crank 72 is engaging the straight length of strip stretching between the spaced rolls 68, 70 and is pulling a new length of strip from the roll 40. As soon as the pulled-off strip has reached the position shown in Fig. 2, the pawl 114 is moved away from the strip by the cam 123 so that the pulled-off length of strip is free to pass over the roll 70 and toward the operating mechanisms of the machine under the action of the feeding mechanism substantially free of tension, or at least under only such relatively light tension as

may be caused by friction as the strip passes over the rolls 70, 88 and 94. In this way, the double-coated upper strip A is supplied to the feeding mechanism of the machine under relatively light tension. It will be seen from the foregoing that the lower pawl 104 is in constant engagement with the strip A while the pawl 114 is in engagement with the strip intermittently. Consequently, the tension on the strip will be varied rather than uniform from the time the strip leaves the supply roll 40 until it enters the ribbed strip forming mechanisms of the machine.

The single-coated lower strip B, as indicated above, is pulled directly from its roll 42 on the reel 46 by the feeding mechanism of the machine, the strip being under very little tension because the windings of the strip are not stuck together on the roll like those of the double-coated strip A. The strip B, with its cemented surface facing inwardly on its roll or upwardly toward the strip A, passes downwardly from the roll around a flanged roll 130 rotatably mounted on a screw 132 (Figs. 3 and 4) threaded into the inner side of the plate 66. It then passes forwardly or toward the left, as viewed in Figs. 1 and 3, under the shaft 74 and through an upstanding guide 134 secured to the base 54 and provided with a vertical slot 136 which twists the strip into a substantially vertical or edgewise position to clear the plate 66, as illustrated in Fig. 3, and guides the strip to the forming mechanism with its cemented surface still facing upwardly toward the upper strip A. The strips A and B are thus supplied to the strip forming mechanism of the machine from the reels 44, 46 in unison and in superimposed relation to each other with the coated surface of the lower strip B facing upwardly toward the double-coated strip A, the feeding mechanism thereafter drawing the strips progressively through the operating instrumentalities of the machine.

Referring to Figs. 16 and 17, the power mechanism of the machine which drives the pulley 82 and shaft 74, above referred to, and also drives the ribbed strip forming mechanisms including the feeding mechanism, is illustrated diagrammatically in Fig. 16 as comprising a motor 138 mounted on the floor or on a lower portion of the machine and rotating a shaft 140 in a counter-clockwise direction as viewed in that figure, the shaft 140 having a pulley 141 thereon connected by the belt 84 to the pulley 82 (Fig. 3) and carrying a second pulley 143 which is connected by a belt 142 to a wheel and pulley 144 rotating continuously on a shaft 146. When it is desired to operate the power mechanism of the machine the shaft 146 is operatively connected to the pulley 144 by a friction clutch and brake mechanism 148 of any well-known construction supported under the base 54 by a bracket 149, as illustrated in Figs. 16 and 17, the clutch 148 being actuated by a treadle 150 connected by a rod 152 to an operating arm 153 projecting rearwardly from the clutch.

The shaft 146 has a grooved collar 154 threaded on its inner end which, together with a washer and nut 155 on its forward end, prevents axial movement of the shaft in the bracket 149. The shaft 146 also carries a three-speed pulley 156 which, through a belt 158 and a pulley and drive wheel 160 (Figs. 13 and 16), rotates the main driving shaft 162 of the strip forming mechanism of the machine in a counter-clockwise direction, as viewed in Fig. 16. The driving shaft 162, as illustrated in Fig. 13, has another pulley 164 se-

cured to its rearward end which, through a belt 166 and a pulley 168 (Figs. 16 and 33) drives a strip winding or reeling mechanism provided on the present machine which will be described hereinafter. The treadle 150 is fulcrumed on a pin 170 mounted in a bracket 172 secured to the base of the machine, the treadle being provided with a rearwardly extending lip 174 which is arranged to catch under a latch 176 when the treadle is depressed to lock the treadle in a depressed position and thus cause the machine to operate continuously until the latch is released by the operator. As illustrated in Fig. 17, the latch 176 is pivoted on a pin 178 mounted in a bracket 180 and is urged forwardly toward the treadle by a spring 182 extending between the latch and the bracket 172.

The pull-off mechanism illustrated in Figs. 1 to 4, inclusive, operates continuously as long as the power is turned on whereas the other operating mechanisms of the machine operate only when the treadle 150 is depressed and latched down as described above. Moreover, the constantly operating pull-off mechanism is not timed or synchronized with the operation of the rest of the machine because by the present arrangement that is not necessary.

It is desirable to prevent damaging the strips or breakage in the machine if, for example, excessive tension of the strips upon leaving their rolls should cause any of the mechanisms to become jammed or locked while the pull-off mechanism continues to operate. Means is provided, therefore, for automatically stopping the machine if the adhesion between the windings of the double-coated strip A, as it is pulled from its roll 40 should be great enough to cause sufficient tension to tear the strip or prevent it from being pulled from its roll by the crank 72. The flanged roll 88 on the lever 90 previously referred to normally acts as an idler roll over which the strip A passes on its way to the forming mechanism. The lever 90 is normally held in a downwardly inclined position against a stop pin 184 by a torsion spring 186 (Figs. 2 and 4) surrounding the pivot 92 and connected at one end to a screw 188 securing a collar 189 to the pivot 92, the opposite end of the spring bearing downwardly against a pin 190 in the lever 90. The spring 186 exerts a downward force on the lever 90 such that a medium tension on the strip A will not move the lever upwardly away from its stop 184 and the roll 88 will then act merely as an idler roll. However, if the tension of the double-coated strip becomes greater than the resistance of the spring 186, it may then be sufficient to tear or break the strip or to cause jamming of the strip forming mechanism and, accordingly, the lever 90 will be elevated away from the stop 184 by reason of the fact that the feeding mechanism has already used up the excess strip provided by the pull-off mechanism on its previous rotation so that, when the crank 72 rotates again into engagement with the strip extending between the rolls 68 and 70, the strip will be substantially straight or taut, as shown in Fig. 1. Since the strip A cannot be pulled from its reel because of the adhesion, continued operation of the feeding mechanism of the machine, in conjunction with the continued rotation of the crank, shortens the length of strip passing from the roll 70 downwardly around the roll 88 and up to the guide roll 94, thereby elevating the lever 90. Upward movement of the lever causes a collar 89 located on the pin 91 forwardly of the roll 88 to engage

the left-hand end of an elongated horizontal lever 192 fulcrumed at 194 on an upstanding bracket 196 secured to the bracket 64. The elongated lever 192 is normally maintained with its left-hand end downwardly against the bracket 64, as illustrated in Fig. 1, by a tension spring 198. The opposite end of the lever 192 has a laterally and downwardly projecting arm 200 which, when the forward end of the lever is elevated by the lever 90 as described, engages a micro-switch 202 in a housing 204 mounted on the bracket 52 and shuts off the electric current to the motor 138, thereby stopping the machine automatically to prevent damage to the strip or machine. The micro-switch 202 is connected in a usual manner by wires 205 to a push button circuit which, in turn, operates a control box (not shown) preferably mounted on the rear portion of the base 54.

It is also desirable in the present machine, in order to increase production, to prevent delays or stoppages in the work. To this end, means is provided for automatically stopping the power driven mechanism of the machine before either of the rolls 40, 42 of the strips A and B on the reels 44, 46 have been completely used up so that it will not be necessary when introducing new rolls into the machine to thread the two strips individually through the successive operating mechanisms, a process which requires considerable time and skill on the part of the operator. The means for automatically stopping the power mechanism before the strips on the rolls 40, 42 are used up comprises a pair of levers 206, 208 (Figs. 1 and 5) pivoted respectively on screws 210, 212 threaded into bosses formed on opposite sides of the standard 50, the levers having enlarged flat surfaces at their upper ends adapted to engage the adjacent sides of the rolls 40 and 42 at points near the centers of the rolls.

The lever 208 is maintained against the forward side of the inner roll 42 by a light tension spring 214 (Fig. 1) connected to the lower arm of the lever and to the housing 204 of the micro-switch 202. The lever 206 is maintained in engagement with the inner side of the front roll 40 by a spring 216 which, through an intermediate offset lever 218 pivoted to the standard 50 by a screw 220, urges the upper end of the lever 206 forwardly against the front roll 40 through the engagement of a pin 222 in the lever 206 with a slot in the upper end of the lever 218. When the strip on either of the rolls 40 or 42 has been used up to a point such that the windings of the roll fall below the flat surface on the corresponding lever 206 or 208, the lever drops off the roll and its lower end opens the micro-switch 202 and shuts off the electric power, thereby stopping the motor 138 and driving mechanism of the machine. Consequently the machine is stopped automatically without attention on the part of the operator when either of the rolls of strip material 40, 42 becomes small enough in diameter to warrant the introduction of a new roll into the machine or, in other words, before either strip is completely used up so that a new roll can be spliced or otherwise attached to the remainder of the strip on the old roll and fed into the machine during its usual operation, thereby obviating the necessity of threading the new strip manually through the various operating mechanisms of the machine.

The strips A and B pass respectively from the roll 94 and guide 134 into the ribbed strip forming mechanisms of the machine in superimposed

relation to each other and at an equal rate of speed under the action of the feeding mechanism as stated above, the double-coated strip A being located above the single coated strip B and the cemented surface of the single coated strip facing upwardly toward the double-coated strip. The strip A enters a folding member 224 illustrated in Figs. 6, 10, 11 and 12, in which the strip is folded progressively upon itself during its feeding movement to form a two-ply layer C (Figs. 19 and 20).

The folding member 224 is mounted on a bracket 226 secured by screws to a table 228 having a cover plate 229 secured thereto, the table supporting the ribbed strip forming instrumentalities of the machine, as illustrated in Fig. 6, and being mounted on upstanding walls 230 secured to a base member 232 fastened by screws to the machine base 54. The folding member comprises a vertical plate 224 provided on its inner or rearward side, as viewed in Fig. 13, with spaced U-shaped wires or staples 234, 236 and 238, the staples being secured in the plate by binding screws 240 and diminishing progressively in size from the staple 234 to the staple 238, as illustrated in Fig. 12. The plate 224 is also provided with a lateral projection or rib 242 (Figs. 11 and 12) located centrally of the openings in the staples and tapering to a relatively thin end adjacent to the smallest staple 238. The strip A is threaded through the staples, as shown in Fig. 12, which, in conjunction with the rib 242, folds the strip progressively during the feeding movement to cause it to emerge from the smallest staple 238 in a folded over position forming a two-ply layer C. As illustrated in Figs. 11 and 12, the plate 224 is cut back at its lower portion to form a step or shoulder 243 which permits the edge of the lower layer of the folded strip to extend beyond the other edge a distance of approximately one-sixteenth of an inch.

The lower strip B enters a slot or guideway 244 (Figs. 18 and 19) formed in the table 228 with the plate 229 overhanging its opposite sides, the strip entering the guideway in a substantially flat position and traveling forwardly or toward the left, as viewed in Fig. 6, below the folded strip A under the action of the feeding mechanism. Upon leaving the folding member 224, the strip A passes into a guideway 246 (Fig. 19) formed by a plate 248 adjustably secured by screws 250 to the cover plate 229, as best shown in Figs. 13, 18 and 19. Adjustably mounted upon the plate 248 by screws 252 is a bracket 254 provided with upstanding ears between which is pivotally mounted on a pin 256 an arm 258 carrying at its left-hand end, as viewed in Figs. 6 and 13, a roll 260 rotatable about a pin 262. At its opposite end the arm 258 carries an adjustable thumb screw 264 which engages the plate 248 for regulating the pressure applied by the roll 260.

Between the bracket 254 and the roll 260 is another bracket 266 having upstanding ears between which is pivoted, on a pin 268 (Figs. 6 and 18), a lever 270 carrying a roll 272 at its rearward end, as viewed in Figs. 13, 18 and 20, the roll 272 being rotatable about a screw 274 threaded into the end of the lever. The lever 270 carries a thumb screw 276 at its opposite end which engages the bracket 266 for regulating the pressure applied by the roll 272. As shown in Fig. 20, the roll 272 is arranged to engage the inner portion of the two-ply layer C of the double-coated strip A after the latter has been folded and to apply pressure to said inner portion as it passes through the guideway 246. Since the strip A is coated on

both surfaces with pressure-responsive cement, the inner portion of the two-ply layer C, which receives pressure from the roll 272, will become firmly bonded together at this stage of the method whereas the remaining portion of the two-ply layer, or left-hand portion as viewed in Fig. 20, will not be bonded together and may be readily separated up to the portion which receives pressure from the roll 272.

After the strips A and B have been acted upon by the roll 272, but before they are engaged by the roll 260, they pass under a folding member 278 adjustably secured to the table 228 by a slot and screw arrangement 279 and adapted to operate upon the lower strip B, as best illustrated in Figs. 18, 20 and 21, by engaging the inner edge of the strip B, as the strips move along their predetermined path, and turning the inner portion of the strip progressively upwardly into the positions illustrated successively in Figs. 20 and 21, the folder 278 then bending said inner portion downwardly around the two-ply layer C into the position shown in Fig. 22 to cover and enclose a portion of the layer C, thereby forming a four-ply layer D. The folding member 278 is shaped as illustrated in Figs. 18, and 20 to 22, inclusive, and is provided with a pair of projections or fingers 280, 281 which extend over the guideway 244 and are shaped to accomplish the folding operation in the manner described during the progressive movement of the strips through the machine under the action of the feeding mechanism. The folder 278 is adjustable laterally of the guideway 244 so that it can be positioned to fold the inner portion of the lower strip B in a manner to leave a portion of the two-ply layer C extending beyond the folded portion of the strip B, for example, one-eighth to one-fourth of an inch. Accordingly, when the strips reach the roll 260, the four-ply layer D has been formed, as illustrated in Fig. 22, except for being positively bonded together to hold the strips permanently in their folded position. The roll 260, in addition to applying pressure progressively to the four-ply layer D to bond the cemented plies thereof permanently together, operates also to assist in maintaining the bonded strips in the guideway 244. The roll 260 has a knurled forward portion 283 adapted to apply relatively heavy pressure to the folded margins of the strips and a slightly beveled but smooth inner portion adapted to apply some pressure to the portion of the folded strips adjacent to the bend therein but primarily to guide the strips in the guideway 244, this result being further facilitated by the folding finger 281 (Figs. 18 and 22) which extends beyond the axis of the roll 260 and likewise tends to confine the strips in the guideway 244. The knurled portion 283 of the roll 260 causes it to be rotated by friction alone as the strips pass thereunder.

It should be pointed out that, although the lower strip B is shown in Figs. 22 and 25 as being folded rather tightly around the two-ply layer C or in such a manner that the layer C completely fills the fold in the strip B, the strip B could, if desired, be folded more loosely around the two-ply layer C so that the latter would not completely fill the fold in the strip B but would leave a space or opening between the folded end of the layer C and the adjacent end of the strip B, this result being readily obtainable by lateral adjustment of the folding member 278 relatively to the guideway 244. Such a construction facili-

tates the formation of a crimp or indentation along the upper portion of the rib during subsequent operations on the composite strip, as will appear hereinafter, this crimp producing a relatively narrow edge along the upper portion of the rib rather than a thick or rounded edge, the narrow edge being more advantageous for some kinds of work.

The combined strips leave the roll 260 and pass forwardly until the four-ply portion D enters a continuation of the guideway 244 in the table 228, the guideway having now been reduced in width at its inner portion by a plate 282 secured to the table 228 by screws 284, as shown in Figs. 13, 24 and 25. Secured to the plate 282 by screws 285 is another plate 286 shaped in plan view, as shown in Figs. 13 and 24, so that its front edge curves forwardly to overlie the reduced guideway 244, as illustrated in Fig. 25, and then swings rearwardly again to clear the guideway. The plate 286 is provided with a hole 288 which registers with a hole in the table 228 through which a needle 290 of stitching mechanism (presently to be described) may operate to insert a row of stitches through the four-ply layer D to secure the plies permanently together along a line preferably spaced a short distance from the left-hand end of the four-ply layer, as viewed in Fig. 25, the plate 286 serving the same purpose as a presser foot in a conventional sewing machine. The guideway 244 is covered at its forward side by a plate 292 (Fig. 13) secured to the table by screws 294 and overlapping the guideway, as shown in Fig. 18 and Figs. 20 to 22, inclusive, to confine the strips as they move progressively through the machine.

Located substantially opposite the needle hole 288 in the plate 286 is a plow 296 adjustably secured to the plate 292 by a screw 298 and having an inner portion 300 which overlies the guideway 244, as illustrated in Figs. 24 and 25, the portion 300 tapering to a relatively thin edge at its lower end, as viewed in Fig. 24, and being arranged to pass under the forward portion of the upper ply of the two-ply layer C and to bend this portion upwardly substantially at right angles to the remaining portions of the strips, as illustrated in Fig. 25, as the strips move progressively along their path, the upturned portion of the two-ply layer C being indicated in Fig. 25 by the letter E and reaching its upstanding position substantially opposite the needle hole 288.

The stitching mechanism of the machine is illustrated in Figs. 6, 10, 14, 23 and 25. The driving shaft 162 has a crank formed on its forward end (Fig. 23), the crank being indicated by the numeral 306 and being balanced by discs 302 and 304 integral with the shaft 162, the latter, forwardly of the disc 302, being concentric with its rear portion. A connecting rod 310 is connected to the crank pin 306 by a bearing cap 308 secured in place by a pair of screws 312. The connecting rod 310 is located within a housing 314 projecting upwardly from the plate 282 and having a pair of bosses 316, 318 (Fig. 23) in its forward portion in which is mounted for heightwise reciprocating movement a needle bar 320 having a needle 290 secured in its lower end by a screw 322.

The connecting rod 310 is connected to the needle bar 320 in a conventional manner by a split collar 324 and screw 326, the collar carrying a pin 328 which extends through the upper end of the connecting rod which, in turn, is held

on the pin by a washer and screw 330. Rotation of the shaft 162 in a counter-clockwise direction, as viewed in Fig. 6, reciprocates the needle bar 320 and needle 290 to insert a single row of stitches S, preferably chain stitches, through the four-ply layer D a short distance from the upturned layer E, as illustrated in Figs. 23 and 25, the needle cooperating in the usual manner with a looper 325 secured to the forward end of the shaft 162 by a set screw 327. The thread, indicated in the drawings by the letter T, may, if desired, be of a color which contrasts with that of the strips, for example, black thread against white or gray strip material, so that the stitches will be plainly visible in the completed strip and will serve as a guide for the operator when lasting or weltting the shoe, the inseam in the weltting operation, for example, being located below the line of stitches in the strip and thereby insuring that the inseam will be positioned low enough on the rib to insure a tight weltting operation.

The thread T may be supplied from any usual source of supply, such as a spool (not shown) and, as illustrated in Fig. 10, may be conducted to the stitching mechanism by a guide rod 329 fastened to the base 54, the thread passing through a conventional tensioning device 331 on the housing 314 in the usual manner and then passing through other guiding members presently to be described forwardly and downwardly to the needle 290 and looper 325, as shown in Figs. 6 and 23, the thread being lubricated by felt pads 332 clamped to the front wall of the housing 314. Fig. 26 shows the combined strips A and B after the row of stitches S has been inserted through the four-ply layer D adjacent to the open end thereof from which the two-ply layer C projects, the upper ply E of said two-ply layer, as stated above, having been turned upwardly out of the plane of said layer to position it at a substantial angle thereto, as illustrated in Figs. 25 and 26. The stitching mechanism, as herein illustrated, inserts a row of chain stitches, the loop of which is located at the lower surface of the four-ply layer D, as viewed in Fig. 25, which surface, in the completed ribbed strip, forms the inner side of the multi-ply rib.

It will be apparent from the foregoing, that the stitching mechanism, as illustrated herein, does not feed or assist in feeding the work through the machine, as is usual in sewing machines, because the needle 290 reciprocates in a vertical direction only with no sidewise or lateral movement for feeding the work. In view of this, the strips must remain stationary while the needle is in the work and the feeding movement can take place only when the needle is removed from the work. The construction and operation of the feeding mechanism and its synchronization with the operation of the stitching mechanism will be described hereinafter. As illustrated in Figs. 6, 23 and 25, the plate 282 which supports the housing 314, carries a guard or shield 334 which extends upwardly in front of the connecting rod 310 and shields the opening between the table 228 and the front wall of the housing 314. The driving shaft 162 normally runs at a reasonable speed, for example, about 1500 to 1700 revolutions per minute although the speed of the shaft can be increased, if desired, up to 3000 R. P. M. without damage to the moving parts.

It is desirable to have the operating mechanisms of the machine, including the stitching

mechanism, cease operating if the thread should break. To this end, means is provided for automatically stopping the machine if the thread breaks, this means being controlled by the tension of the thread T. Mounted on the upper portion of the housing 314 is a bracket 336 (Figs. 6 and 10) having adjustably secured thereto by screws 338 an upstanding bracket 348 carrying on its upper end a box containing a micro-switch 342. The thread T passes upwardly from the tensioning device 331, through an upstanding thread guide and controlling member 344 fastened to the housing 314, the member 344 being provided with a leaf spring 345 secured to its lower portion by a screw 347 for controlling the thread. The thread passes downwardly from the member 344 through a thread guide 335 (Fig. 14) and an eye 346 formed on the front of the housing 314 and continues downwardly through the felt pads 332 to the needle 290. The upper end of the needle bar 320 has a horizontal take-up plate 348 secured thereto by a screw 350 and carrying a headed pin 352 which supports a torsion spring 354, one end of which projects toward the left, as viewed in Figs. 6 and 14, into a position just behind the micro-switch 342. The thread T, as shown in Figs. 14 and 23, passes over the take-up plate 348 and the projecting end of the spring 354 as it passes downwardly to the needle.

The micro-switch 342 is provided with a switch lever 356 (Fig. 10) in the form of a leaf spring which tends normally to snap rearwardly, as viewed in Fig. 14, to open the micro-switch and shut off the electric current, thereby stopping the motor 138 through a wire connection 358 extending between the micro-switch and the control box referred to. Pivoted on the micro-switch is a small latch 360 (Figs. 10 and 14) which extends rearwardly and normally engages the leaf spring 356 and holds it forwardly, as viewed in Fig. 14, to prevent the spring from opening the micro-switch. When the needle bar is in its lowermost position, the thread T passes loosely over the projecting end of the torsion spring 354, so that the torsion spring is located in a more forward position than is shown in Fig. 14, or so that the left-hand end of the spring is positioned directly below the latch 360. As the needle bar moves upwardly with the thread extending over the take-up member 348, the thread becomes tensioned to pull the stitch tight in the work. This upward movement of the needle bar and take-up means 348 finally, near the upper end of each stroke, tightens the thread passing over the projecting portion of the torsion spring 354 and pulls the spring rearwardly, as viewed in Fig. 14, to move it out of the path of the latch 360. Consequently, the latch 360 is not lifted to release the leaf-spring switch 356 to open the micro-switch and stop the machine during its normal operation or when the thread is not broken. If, however, the thread should break, elevation of the needle bar and take-up means 348 will not tighten the thread as described above so that the end of the torsion spring 354 will not be moved rearwardly out of the path of the latch 360. Consequently, the spring 354 will strike the latch and lift it away from the leaf-spring switch 356, thereby permitting the latter to snap rearwardly against a stop 362 on the housing of the micro-switch 342 and shut off the power to stop the machine through the connections to the control box referred to above. Since the power-operated mechanisms of the machine, as illustrated in Fig. 16, are all

driven from the single motor 138, opening of the micro-switch 342 will stop all the operating mechanisms of the machine simultaneously. The micro-switches 202 (Fig. 1) and 342, and other micro-switches to be described hereinafter, are all located in switch boxes or housings and are wired in series with a push button circuit (not shown) in the usual manner, the push button circuit operating the control box above referred to which is preferably located on a rear portion of the base of the machine.

It should be pointed out that, while it may be desirable in some cases to insert the stitches S through the four-ply layer D of the strip because some manufacturers may prefer the stitches in order to strengthen the finished strip or to provide visible means to serve as a guide in the lasting or welting operations, it is not necessary in order to construct the present ribbed strip that stitches be inserted through the layer D. In other words, the completed ribbed strip will be just as strong and will retain its shape just as well if the stitches S are omitted. The mechanism has been arranged, therefore, so that the stitching mechanism can be readily rendered inoperative, if desired, without effecting the operation of the other mechanisms of the machine, thereby permitting the composite strip to be made without stitches extending through the four-ply layer D. In order to render the stitching mechanism inoperative, it is necessary merely to remove the connecting rod 310.

The combined strips A and B, folded and stitched as shown in Fig. 25, now pass progressively forwardly or to the left under the action of the feeding means and, as illustrated in Figs. 13, 24 and 26, are gradually turned bodily as a unit so that the four-ply layer D, which forms the rib in the completed strip, extends downwardly in a substantially vertical position as shown in Fig. 28, thereby positioning the composite strip for the next operation to be performed thereon. The means for turning the strip bodily consists of a downwardly inclined surface 364 (Fig. 26) provided on the lower side of the plate or presser foot 286, the surface 364 engaging the four-ply layer D after it leaves the stitching mechanism and bending it downwardly, as shown in Figs. 26 to 28, inclusive, into the vertical position referred to. The remaining portions of the composite strip, that is, the portions of the two-ply layer C which project beyond the four-ply layer D, and the portion of the lower strip B which extends beyond said two-ply layer, are now free of the guideway 244 in the table 228 because the guideway terminates a short distance to the left of the stitching mechanism, as viewed in Fig. 24, approximately in line with the plow 296. A plate 366 is adjustably secured to the table 228 by a screw 368 opposite the inclined surface 364 on the plate 286, the plate 366 extending to the end of the table 228 and both the plate and table being cut away at their inner edge portions, as shown in Figs. 26 to 28, to provide sufficient space to permit the strip to be turned approximately 90°. The remaining portions of the composite strip, that is, the laterally extending portion E, the other ply of the two-ply layer C, and the marginal portion of the lower strip B which extends beyond said two-ply layer, are now free of support from below and can be turned with the four-ply layer D, said other ply of the two-ply layer C being indicated in Fig. 26 by the letter F, and the portion of the lower strip B projecting beyond this ply being indicated by the letter G.

It will be seen in Figs. 26 to 28, inclusive, that the inclined surface 364 on the plate 286 swings gradually downwardly into a vertical plane to turn the four-ply rib D into its vertical position. 5 At the same time, a surface 370 on the plate 286, adjacent to the surface 364, curves gradually rearwardly from a vertical position into the horizontal plane shown in Fig. 28. Consequently, as the rib D is swung downwardly, the portion E of 10 the upper strip A is permitted to swing rearwardly and downwardly as the strip moves progressively along its path, this action being assisted by a presser member or arm 372 (Figs. 24 and 28) adjustably secured to the plate 366 by a screw 374 15 (Fig. 24) and having an inner portion 376 arranged to overlie the turned strip and to engage the base portion of the strip, as illustrated in Fig. 28, the portion 376 of the arm laying the portion E of the strip firmly against the horizontal surface 370 and also engaging the remaining portions F and G, which project from the rib D in an opposite direction to the portion E, the projecting portions E and FG now forming substantial angles 20 relatively to the four-ply rib D.

25 After passing under the member 372, the ribbed strip, hereinafter designated generally by the letter H when referred to as a unit, travels progressively toward the left, as viewed in Fig. 6 and passes through a guide 378 (Figs. 6 and 7) 30 secured to the wall 230 by screws 380 and provided at its upper end with a U-shaped slot 382 arranged to receive the rib D and guide the strip in a proper lateral position between a pair of cooperating rolls 384, 386 constructed and arranged to apply pressure progressively to the composite strip to shape the rib and the laterally extending portions E and FG and also to 35 bend the portion FG into a still further inclined position relatively to the rib D, the portions E and FG forming outer and inner flanges on the rib after they have been caused to project laterally from opposite sides of the base of the rib as described.

The rolls 384, 386, which incidentally form 40 part of the feeding mechanism of the machine, are shaped as illustrated in Figs. 8 and 29, the upper roll 384 being larger in diameter than the roll 386 so that, as the rolls are rotated at equal speeds in opposite directions in a manner to be presently explained, the upper roll 384 will exert a downward wiping pressure upon the portion of the strip engaged thereby, namely, the flange FG, due to the greater surface speed of the roll 384 and will thereby produce a relatively sharp 45 bend or crease along the base of the rib D between the rib and the flange FG, as illustrated in Fig. 29. The roll 384 has an inclined surface 388 on its periphery which is preferably knurled or roughened to create friction between it and the strip, the lower roll 386 having a similarly 50 inclined surface 390 cooperating with the surface 388. The roll 386 is provided with an annular slot 392 adapted to receive the rib D and maintain it in its downwardly extending position 55 as the composite strip H passes between the rolls. As stated above, the rolls form part of the feeding mechanism of the machine for drawing the strips progressively therethrough, the knurled surface 388, in conjunction with the pressure applied by the rolls, creating sufficient 60 friction to accomplish this result.

The mechanism for operating the feed rolls 384, 386 is illustrated in Figs. 10 and 15. The upper roll 384 is secured to the forward end of a 65 shaft 394 rotatably mounted in bearings 396,

398 supported in a housing 400 provided on a horizontal extension 402 on the base 232. The shaft 394 has a gear 404 secured thereto between the bearings 396, 398 by a pin 406, the shaft being maintained against axial movement by the gear 404 and a collar 408 pinned to the inner end of the shaft and engaging the rear bearing 398. The lower roll 386 is secured to the forward end of a shaft 410 journaled in bearings formed in a lower portion of the housing 400, the shaft having a gear 412 secured to it by a pin 414 and meshing with the gear 404.

The upper feed roll 384 is adjustable toward or away from the lower roll 386 by reason of the fact that the rear bearing 398 is pivotally supported between opposite side walls of the housing 400 by a pair of conical screws 416 (Figs. 13 and 15) while the forward bearing 396 is movable heightwise between the opposite walls of the housing, the housing having a cover plate 418 secured thereto by screws 420 and carrying a thumb screw 422 which is arranged to engage the forward bearing 396 and limit its upward movement in the housing. The position of the roll 384 relatively to the lower roll 386 is determined by an adjustable screw 424 threaded through the bearing 396 and engaging a solid portion of the housing 400. By this construction the rolls may be adjusted into positions to cause them to exert relatively heavy pressure upon the composite strip H as it passes therebetween.

The shafts 394 and 410 are driven equal amounts in opposite directions to operate the rolls by the mechanism best illustrated in Figs. 10, 13 and 15. The lower shaft 410 projects rearwardly beyond the housing 400 and is provided at its inner end with a Horton clutch device 426 of well-known construction having an upstanding arm 428 secured to its inner side by a screw 430, a reduced end 432 of the shaft 410 passing through a hole in the arm to hold it rigidly in position. Adjustably secured in a vertical slot (not shown) in the arm 428 is a slide block 433 carrying a stud 434 which, through a universal joint 436 and a connecting rod and strap arrangement 438 (Fig. 10), is pivotally connected to an eccentric 440 secured by a pin 441 to an inner portion of the driving shaft 162, as shown in Fig. 13.

The shaft 162 is journaled in upstanding bosses 442 and 444 formed on a rear portion of the base 232, the base preferably having feet 446 thereon whereby it may be rigidly fastened by screws 448 to the machine base 54. The shaft 162 is maintained against axial movement in its bearings by the disk 304 (Fig. 28), which engages the front bearing 442, and by a collar 450 (Fig. 13) which engages the front bearing 442 and is secured to the shaft by a set screw 452. Rotation of the shaft 162 in a clockwise direction, as viewed in Fig. 10, causes the eccentric 440 to oscillate the arm 428 and Horton clutch 426 about the axis of the lower shaft 410. Each oscillation of the Horton clutch in a clockwise direction turns the shaft 410 in the same direction while, on its reverse movement, the clutch releases the shaft and does not turn it. Consequently, the shaft 410 is rotated intermittently in a counterclockwise direction, as viewed in Fig. 6, and the upper shaft 394 is rotated intermittently an equal amount in an opposite direction by reason of the gears 412, 404. The rolls 384 and 386 are thus driven intermittently in proper directions to draw or feed the composite strip

H progressively through the operating mechanisms of the machine.

As indicated above, the stitching mechanism does not assist in feeding the strip through the machine because the needle moves in a vertical direction only when inserting the stitches S. Obviously, since the strips must remain stationary while the needle 290 is engaged in the work, the feeding movement of the strips can take place only when the needle is elevated from the work. The arrangement of the crank 306 relatively to the eccentric 440 and its associated mechanism is such that the rolls 384, 386 are stationary when the needle 290 is engaged in the work, the rotation of the rolls taking place when the needle leaves the work and continuing until it re-enters the work to form another stitch. Consequently, the strip H is fed intermittently by the rolls 384, 386 in synchronized relation to the operation of the stitching mechanism of the machine.

The composite strip H, in the condition shown in Fig. 29, that is, with the two-ply layer FG, which forms the inner flange of the completed strip, bent at an acute angle to the four-ply rib 25 D and with the outer flange E located substantially at right angles to the rib, passes forwardly from between the rolls 384, 386 and toward the left, as viewed in Figs. 6 and 13, under a guide member 454 secured by a screw 456 to a block 458 which, together with a similar block 460, is secured by screws 462 to a rectangular housing 464 fastened by screws 466 to the left-hand end of the plate 402. The blocks 458, 460 support a plate 468 upon which is secured by screws 470 a thin plate 472 which, together with the plate 468 as shown in Figs. 13 and 30, forms a guideway 474 through which the strip H passes after leaving the guide member 454. The strip then passes under a flat member 476 secured to the plate 472 by a screw 478 and having a forward edge 479 which extends diagonally across the guideway 474 and is adapted to engage the upwardly facing surfaces of the flange portions of the strip and maintain them in a relatively flat position as the strip passes through the guideway 474.

The strip H next passes between a pair of rolls 480 and 482 which perform a final shaping and flattening operation upon the strip after it has been positioned in the guideway 474 in the manner described above. The rolls 480, 482, as illustrated in Fig. 6, are mounted in a housing 464 in substantially the same manner as the rolls 384, 386 in the housing 400, the two housings being interconnected by a brace 484 secured thereto by screws 486 and the screws 420 previously referred to. As illustrated in Fig. 9, the upper roll 480 is secured to a shaft 488 which is adjustable toward or away from a lower shaft 490 carrying the roll 482, the adjustment being effected by a screw 492 similar to the screw 424 and the rolls being maintained against separation by a thumb screw 494.

The shapes of the rolls 480 and 482 are best illustrated in Figs. 9 and 30 in which it will be seen that the forward portion of the upper roll 480 is cylindrical in shape and preferably knurled for engaging the two-ply inner flange FG, the roll also having a frusto-conical inner portion 496 adapted to engage and apply substantial pressure to the portion of the inner flange FG adjacent to the rib D. The lower roll 482 has a forward portion 498 which is larger in diameter than its inner portion and forms a step or shoulder therewith, the portion 498 being adapted to engage 70 the upper portion of the four-ply rib to seal the

plies thereof firmly together and also to form a crimp or crease therein to insure that the rib will have a relatively narrow top portion as distinguished from a thick or rounded top edge. As shown in Fig. 30, the reduced inner portion of the roll 482 is cylindrical in shape and is arranged, in cooperation with the frusto-conical portion 496 of the upper roll, to squeeze the remainder of the strip tightly together and thereby put the strip in such a condition that, when the pressure of the rolls is relieved, the strip will tend to remain temporarily in the relatively flat condition illustrated in Fig. 30 for a sufficient period of time to permit the strip to be wound upon a spool or reel while in a flat condition.

As stated, the rolls 480, 482 are driven in the same manner as the rolls 384, 386. The shaft 490 of the lower roll carries at its rearward end a Horton clutch 500 (Fig. 10) with a vertical arm 502 secured to the clutch by a screw 503 and having an elongated slot 504 in which a slide block 506 (Fig. 10) is adjustably secured by a nut 508. The block 506 is connected by a coupling 510 and rod 512 to a coupling 514 (Figs. 10 and 15) which, in turn, is connected to a slide block 516 secured in the slot in the arm 428 associated with the Horton clutch 426. Consequently, intermittent rotary movement of the rolls 384, 386, in the manner explained, will, through the connections described above, transmit a corresponding intermittent rotary movement, more or less as desired, to the rolls 480, 482 the Horton clutch 500 acting the same as the clutch 426 and the shafts 488 and 490 being interconnected by gearing 518 (Figs. 13 and 33) as previously described. It will be apparent, therefore, that intermittent rotation of the rolls 480, 482 will take place only when the needle 290 is elevated from the work in the same manner as intermittent rotation of the rolls 384, 386.

The strip H now passes toward the left, as viewed in Figs. 6, 13 and 33, out of the guideway 474 and, after passing under a guide or holdown 520 (Fig. 33) secured by a screw 521 to the plate 468, travels around a concave roll 522 rotatable about a pin 524 mounted in an upstanding bracket 526 bolted to the base 54. The strip passes upwardly from the roll 522 between a pair of small spool-shaped rolls 528 and 530, the roll 528 being rotatable about a stud screw 532 secured by a nut 533 in the upper end of a lever 536 (Figs. 33 and 35), and the roll 530 being fixed against rotation on a screw 534 mounted in said lever. The lever 536 is arranged to guide the strip H onto a reel 538 forming part of the winding mechanism on the machine for automatically winding the temporarily flattened strip onto a reel preparatory to its use on insoles or, if desired, for storage or for shipment to shoe manufacturers.

As illustrated in Figs. 33 to 36, inclusive, the winding mechanism of the machine comprises a horizontal shaft 540 journaled in an elongated bearing 542 provided at the upper end of a standard 544 formed on the base 54. At its right-hand portion, as viewed in Fig. 35, the shaft 540 carries the reel 538 which is removably secured on the shaft against a flanged collar 546 by means of a retaining disc 550 and nut 552, the collar 546 being fastened to the shaft by a set screw 548. As illustrated in Fig. 35, the lever 536 is located substantially centrally of the reel 538.

At the opposite side of the bearing 542, the shaft 540 has a constantly rotating pulley 554 mounted thereon, the pulley being positioned between a pair of clutch plates 556, 558 of usual

construction between which and the pulley are located friction washers 561. The clutch plate 556 is fastened to the shaft 540 by a set screw 557 and the plate 558 is secured thereto by a screw 559 having a small end which fits into a horizontal spline 563 in the shaft so that the clutch plate will rotate with the shaft but can also move longitudinally thereof. A compression spring 560 bears against the clutch plate 558 and normally urges the clutch members together, thereby creating friction between the pulley and clutch plates 556, 558 to rotate the shaft 540. The spring 560 is held on the shaft by a nut 562 threaded thereon and providing means for adjusting the tension of the spring against the clutch members.

The pulley 554 is rotated continuously on the shaft 540 by a belt 564 which travels downwardly over a pulley 566 keyed to a shaft 568 positioned at right angles to the pulley 554 in a gear reduction box 570 bolted to the base 54, the gear box 570 having an upper shaft 572 journaled therein parallel to the shaft 540 and upon which the pulley 168 previously referred to is mounted (Figs. 16, 33 and 35), the pulley 168, as explained above, being driven from the motor 138 through the chain of mechanism illustrated diagrammatically in Fig. 16. In the normal operation of the machine, the pulley 554 rotates continuously on the shaft 540 and, through the friction clutch elements 556, 558 and 561, rotates the shaft 540 and reel 538 to cause the ribbed strip H to be wound automatically upon the reel, as illustrated in Fig. 35.

The ribbed strip H coming from the machine may be initially secured to the reel 538 by adhesive tape or tacks. The tension on the friction clutch by the spring 560 will be initially set by the nut 562 to a sufficient amount to cause the clutch, through the pulley 554, to rotate the shaft 540 when the reel is substantially full, thereby insuring that the winding mechanism will rotate whether the reel is full or empty. When the windings first start on the reel there will be little or no slipping of the pulley on the shaft 540 to permit the reel to slow up because less power or friction is required to drive the shaft when the diameter of the reel is relatively small. As the diameter of the reel increases, through additional windings of the strip thereon, the shaft 540 and reel will gradually rotate a little slower than the pulley 554, the clutch permitting the pulley to slip on the shaft 540 since greater friction is required by the clutch to rotate the larger reel as it pulls the strip from the machine. As stated above, the tension of the spring 560 is set initially to provide sufficient friction to insure that the clutch will rotate the reel when it is substantially full. Accordingly, the strip will be wound automatically upon the reel irrespective of the number of windings thereon or the diameter of the reel when full, the windings nearer the outer portion of the wound strip, however, being wound somewhat looser on the reel than the windings nearer the core of the reel because of greater slippage of the pulley on the shaft 540 as the diameter of the reel increases.

The lever 536, which guides the strip H to the reel and causes it to be distributed substantially evenly across the width of the reel, is pivoted on a pin 574 secured in a bracket 576 mounted on the base 54. Above its pivot, the lever 536 carries a roll 578 which rides in a heart-shaped cam track 580 formed in a cam 582 secured by a nut 583 (Fig. 33) to the reduced end of a shaft 584 rotatably mounted in bearings formed in a brack-

et 586 fastened by screws to the machine base 54. The shape of the cam track 580 is such that, as the shaft 584 is rotated, the lever 536 will be swung slowly back and forth about its pivot 574 in an arc below the circular ends of the reel 538, thereby guiding the strip H onto the reel in a manner to insure a substantially uniform winding of the strip across the width of the reel.

The roll 578 is mounted on the lever 536 for adjustment widthwise thereof. The pin 585 which carries the roll passes through aligned horizontal slots 587 (Fig. 35) formed widthwise through the lever and a plate 589 secured to the forward side of the lever, as viewed in Fig. 35, the pin 585 being secured in position in the slots by a nut 591 threaded on a reduced end of the pin. This construction permits the lever 536 to be adjusted widthwise about its pivot 574 relatively to the roll 578 in the fixed cam track 580 so that the lateral movement of the lever can be initially positioned or centralized relatively to different reels which may vary considerably in width. Before adjusting the lever, the cam 582 is turned manually into a position in which the roll 578 is either at the highest or the lowest part of the cam track 580. Loosening of the nut 591 then permits the lever to be swung laterally relatively to the stationary roll in the cam slot until the upper end of the lever is located in the desired position relatively to the reel 538, after which the nut is tightened to maintain the adjustment.

The lever 536 is also adjustable heightwise to produce more or less lateral movement of the lever for reels of different sizes, the adjustment being conveniently obtained by forming the lever in two parts, as shown in Figs. 33 and 35, and by connecting these parts by a plate 593 rigidly secured by screws to the lower part of the lever, the upper part having vertical slots 595 (Fig. 35) therein whereby said upper part may be fastened to the plate 593 for heightwise adjustment relatively thereto by screws 597 passing through the slots 595 and into the plate. When the reel 538 is changed, the length of the lever 536 can be varied as much as may be necessary to produce the proper amount of lateral swinging movement for the size of the reel being used, the lever being also positioned at that time relatively to the reel by the widthwise adjustment described above to insure that this swinging movement is located substantially centrally widthwise of the reel.

The shaft 584 has a spiral gear 588 secured thereto between its bearings in the bracket 586 which meshes with a spiral gear 590 pinned to a lower shaft 592 journaled at right angles to the shaft 584 in the bracket 586. At its left-hand end as viewed in Fig. 35, the shaft 592 carries a sprocket 594 which, by means of a chain 596, is connected to a sprocket 598 secured to the upper shaft 540, the upper sprocket and a portion of the chain being enclosed in a guard member 600 secured by a screw 602 to the standard 544. Rotation of the shaft 540 rotates the lower shaft 584 and cam 582 thereby swinging the lever 536 laterally back and forth relatively to the reel 538 to distribute the strip thereon in the manner described.

It is desirable to stop the machine when the reel 538 is full, or as full as may be desired, without attention on the part of the operator so that, through the stopping of the machine, the operator will see that the reel should be changed and will remove the reel from the machine and mount an empty reel therein. To this end the machine is provided with mechanism for auto-

matically stopping the power-operated mechanism of the machine when the reel 538 is full, or if desired, when a predetermined amount of the ribbed strip has been wound upon the reel. Projecting upwardly from the base 54, rearwardly of the reel 538, or to the left as viewed in Fig. 33, is a narrow column or post 604. Pivoted on a screw 606 in the upper end of one side of the post 604 is an elongated plate-like lever 608 at the forward portion of which is pivoted on a screw 610 a downwardly curving arm 612 carrying at its forward end a small transverse rod 614 of sufficient length to span the space between the opposite circular ends of the reel 538 or, if desired, to pass between said ends without striking them. Secured to the opposite side of the lever 608 by a right-angle bracket 616 is a housing 618 for a micro-switch which is connected in series by wiring 620 with the other micro-switches to the push button circuit referred to and thence to the control box, as described above, the micro-switch having a leaf-spring switch 622 projecting therefrom, the end of which is positioned just above the transverse rod 614 on the arm 612 when the latter is located in its lowermost position against a stop pin 624 in the lever 608. When the windings of the ribbed strip H on the reel 538 become sufficiently large in diameter, for example, when the reel is substantially full, as illustrated in Fig. 36 or diagrammatically in Fig. 34, the strip will strike the transverse rod 614 at some point along its length and lift the rod into engagement with the switch 622, thereby opening the micro-switch to shut off the electric current and stop the machine.

The lever 608 is normally located in a predetermined angular position on the post 604 against a vertical stop screw 626 threaded through a projection on the post and engaging the lever 608, the latter being held against the stop screw by a spring 628 extending between the lever and the upper end of the post. A compression spring 630 surrounds the stop screw 626 to maintain it in adjusted position. Adjustment of the stop screw varies the angular position of the lever as desired for different reels without changing the relation of the transverse rod 614 to the leaf-spring 622. When the reel 538 becomes full, or when the windings of the strip H upon the reel become sufficiently large in diameter to warrant removal of the reel and the introduction of an empty reel, the mechanism described above operates automatically to stop the machine, thereby permitting the full reel to be removed from the machine and a new reel to be mounted therein, the stopping of the machine taking place without attention on the part of the operator. In removing the reel, the length of ribbed strip extending between the guide rolls 528, 530 and the reel may be cut with a knife or scissors and, when the new reel is mounted on the shaft 540, the severed end of the strip may be guided to the reel by hand and secured thereto by adhesive tape or tacks after which the winding of the strip upon the reel will proceed automatically.

Figs. 31 and 32 illustrate completed ribbed strips H constructed in accordance with the method of the present invention practiced with the aid of the improved machine disclosed herein. As shown in these figures, the composite strip is secured by pressure alone to the outer surface of an insole I by means of the pressure-responsive cement on the bottom surfaces of the inner and outer flanges FG and E, and on the bottom surface of the inwardly extending portion of the

upper layer of the inner flange FG, this cement, as explained above, combining with the same kind of cement previously applied to the marginal portion of the insole to produce a strong adhesive bond. The composite strip is provided with an upstanding four-ply rib D approximately one-fourth of an inch in height, the plies of which are secured together by the pressure-responsive cement on the strips or, in Fig. 31, by this cement plus the stitches S which pass widthwise through the rib adjacent to the base or flange portion thereof. The strip has a single ply outer flange E approximately one-eighth of an inch in width adapted to overlie the feather portion of the insole, and it has a two-ply inner flange of substantially the same width, the upper layer of which extends inwardly a substantial distance beyond the two-ply flange to provide a wide reinforcement for the insole. The rib is inclined inwardly toward the inner flange FG at an angle of approximately 60° to the horizontal to improve the utility of the rib and to facilitate subsequent operations during the construction of the shoe. Although the strip is shown on a greatly enlarged scale in the drawings so that some of its features may be slightly exaggerated, it will be seen that the upper edge portion of the four-ply rib is relatively thin or narrow in shape rather than being thick and rounded as is more usual in such constructions, this feature tending to render the strip somewhat more flexible lengthwise than in other constructions and thereby facilitate its application to the insole.

The completed strip H is also singularly free of any tendency to curve or curl lengthwise before it is applied to an insole and a relatively long length of the completed strip can be positioned without effort in a substantially straight line or path without any undue tendency of the strip to curve or curl out of such path. This feature of the strip is due primarily to the method of its construction, particularly to those steps of the method which insure that the double-coated strip is supplied to the feeding and forming mechanisms under relatively light tension, and also the steps which require that one strip shall be folded to form the two-ply layer before the other strip is folded around said two-ply layer to form a four-ply layer, thereby eliminating any tendency of the combined strips to strap or bind during the formation of the four-ply layer and thus set up forces or tensions in the material of the strip which would tend subsequently to cause the strip to curve or curl out of its relatively straight condition.

It will be noted in Figs. 31 and 32, that the portion of the strip directly below the rib D is securely bonded to the surface of the insole I because, due to its method of construction, the base or flange portion of the strip in the present embodiment comprises a substantially flat unbroken surface rather than a surface having a space or pocket below the rib, as is sometimes the case in other constructions of this general type. It should also be pointed out that, while the rib D is sufficiently stiff and rigid to afford an excellent shoulder or abutment against which to last a shoe upper, or to which to attach the upper and welt, it is nevertheless flexible widthwise to a considerable degree, that is, the rib can hinge or pivot laterally under sufficient pressure about an axis located approximately on the longitudinal median line of the base of the rib, this pivoting action, however, being only in response to external pressure applied to the rib

so that, after the pressure is relieved, the rib tends to return to its normal inwardly inclined position illustrated in Figs. 31 and 32. Since the rib portion of the strip is not unduly stiff or unyielding widthwise, it can bend or flex inwardly or outwardly under pressure during operations on the shoe such, for example, as the lasting and weltng or inseaming operations. This feature of the rib being able to bend or pivot laterally relatively to its base portion not only increases the flexibility of the rib and insole but prevents the rib from weakening or breaking the cement bond between the flange portions of the strip and the insole margin particularly at the portion of the strip underlying the rib, as sometimes occurs in ribbed strips in which the rib is stiff or rigid relatively to its base portion so that pressure inwardly or outwardly against the rib sometimes causes the rib to act as a lever and lift or break the base portion of the strip away from the insole at some portions thereof, thereby weakening the attachment of the strip to the insole and also permitting the inseam stitches to pass completely under the rib which, of course, results in a poor inseaming operation. As stated above, the ribbed strip of the present invention is adapted to be applied immediately to insoles as it leaves the strip forming machine, in which case the strip would be guided directly to a ribbed strip applying machine as it leaves the shaping and flattening rolls 480, 482 without passing into the automatic winding mechanism or, if desired, the completed strip may be permitted to pass into the winding mechanism and be automatically wound upon a reel for storage or shipment.

Having thus described my invention, what I claim as new and desire to secure by Letters Patent of the United States is:

- 40 1. A machine for making ribbed strips for attachment to insoles to provide sewing ribs thereon having, in combination, mechanism for feeding strips of indefinite length in unison, a member for folding one of said strips during said feeding movement to form a two-ply layer, and means for folding another one of said strips progressively around said two-ply layer to form a four-ply layer with remaining portions of said two-ply layer and other strip projecting therefrom, said means acting also to bend said remaining portions laterally relatively to said four-ply layer to produce a composite strip having a multiply rib and flanges projecting laterally from the base of said rib.
- 45 2. A machine for making ribbed strips for attachment to insoles to provide sewing ribs thereon having, in combination, mechanism for feeding a pair of strips progressively, a member for folding one of said strips during the feeding movement to form a two-ply layer, and means for progressively folding the other strip around said two-ply layer to cover a portion thereof and form a four-ply layer with the remaining portions of said two-ply layer and other strip projecting beyond said four-ply layer, said folding means acting also to bend said remaining portions of the two-ply layer and other strip into lateral positions relatively to the four-ply layer to produce a composite strip having a four-ply rib with flanges projecting laterally from the base of said rib.
- 50 3. A machine for making ribbed strips for attachment to insoles to provide sewing ribs thereon having, in combination, mechanism for feeding a pair of strips at equal speeds, a member for

folding one of said strips progressively during the feeding movement to form a two-ply layer, and stationary means for folding the other strip around approximately half of said two-ply layer during the feeding movement to enclose said portion and form a four-ply layer from which the remaining portions of the two-ply layer and other strip project, said stationary means operating also to bend the remaining portions of said two-ply layer and other strip progressively into angular positions relatively to the four-ply layer to produce a composite ribbed strip provided with an upstanding four-ply rib having flanges extending laterally from the base thereof.

4. A machine for making ribbed strips for attachment to insoles to provide sewing ribs thereon having, in combination, mechanism for feeding a pair of strips in unison, a member for folding one of said strips progressively during the feeding movement to form a two-ply layer, and means for folding the other strip progressively around said two-ply layer to cover a portion thereof and form a four-ply layer from which the remaining portions of the two-ply layer and other strip project, said means being also arranged to bend the plies of the remaining portion of said two-ply layer in opposite directions to position them at substantial angles to the four-ply layer, thereby producing a composite strip having a four-ply rib and inner and outer flanges at the base of said rib.

5. A machine for making ribbed strips for attachment to insoles to provide sewing ribs thereon having, in combination, mechanism for feeding a pair of strips in substantially parallel relation to each other, a fixed member for folding one of said strips upon itself during the feeding movement to form a two-ply layer, and means for progressively folding the other strip around a portion of the two-ply layer to enclose said portion and form a four-ply layer with the remaining portions of said two-ply layer and other strip extending beyond the four-ply layer, said folding means being also arranged to bend the plies of the extending portion of the two-ply layer into oppositely disposed positions relatively to said four-ply layer to form inner and outer flanges thereon, said other strip overlapping one of said flanges and extending a substantial distance beyond said flange.

6. A machine for making ribbed strips for attachment to insoles to provide sewing ribs thereon having, in combination, mechanism for feeding a pair of strips at the same speed, a member for folding one of said strips during such movement to form a two-ply layer, means for applying pressure progressively to said two-ply layer, stationary means for folding the other strip around said two-ply layer to enclose a portion thereof and form a four-ply layer with the remaining portions of said two-ply layer and other strip projecting therefrom, and means for progressively bending said remaining portions of the two-ply layer and other strip into lateral positions relatively to said four-ply layer to produce a composite strip having a four-ply rib with flanges projecting laterally from said rib.

7. A machine for making ribbed strips for attachment to insoles to provide sewing ribs thereon having, in combination, mechanism for feeding a pair of strips of indefinite length in superimposed relation to each other, means for guiding said strips, a member for folding the upper strip during the feeding movement to form a two-ply layer, stationary means for folding the

lower strip progressively around said two-ply layer to cover a portion thereof and form a four-ply layer with the remaining portions of said lower strip and two-ply layer projecting from one end of said four-ply layer, and means for bending the plies of the projecting portion of said two-ply layer progressively in opposite directions during said feeding movement to position said plies at substantial angles to said four-ply layer, thereby producing a ribbed strip having a four-ply rib with inner and outer flanges projecting laterally from opposite sides of the base of said rib.

8. A machine for making ribbed strips for attachment to insoles to provide sewing ribs thereon having, in combination, mechanism for feeding a pair of strips at equal speeds, a guide for positioning said strips relatively to each other, a member for folding one strip upon itself during the feeding movement to form a two-ply layer, means for progressively folding the other strip around a portion of the two-ply layer to form a four-ply portion with the remaining portions of the two-ply layer and said other strip extending from one end of said four-ply portion, and means for progressively bending the plies of the remaining portion of said two-ply layer into oppositely extending positions relatively to said four-ply portion to produce a composite strip having a four-ply rib with flanges projecting laterally from opposite sides of the rib, one of said flanges being covered by the remaining portion of said other strip to provide a two-ply flange at one side of the rib.

9. A machine for making ribbed strips for attachment to insoles to provide sewing ribs thereon having, in combination, mechanism for progressively feeding a pair of strips in unison, a fixed member for folding one of said strips widthwise during the feeding movement to form a two-ply layer, a guide for positioning said two-ply layer relatively to the other strip, a roll for applying pressure progressively to said two-ply layer, means for progressively folding said other strip around a portion of said two-ply layer to cover said portion and form a four-ply layer with the uncovered portion of the two-ply layer projecting therefrom, and means for bending the plies of said uncovered portion of the two-ply layer in opposite directions to position them substantially at right angles to the four-ply layer to produce a composite strip having a four-ply rib with flanges extending laterally from opposite sides of the rib, one of said flanges being covered by said other strip which extends beyond said flange to provide a wide reinforcement for the insole.

10. A machine for making ribbed strips for attachment to insoles to provide sewing ribs thereon having, in combination, mechanism for feeding a pair of strips in superimposed relation to each other, a member for folding the upper strip during the feeding movement to form a two-ply layer, means for folding the lower strip progressively around said two-ply layer to cover a portion thereof and form a four-ply layer with the remaining portions of said two-ply layer and lower strip projecting beyond said four-ply layer, and means for bending the plies of said remaining portion of the two-ply layer in opposite directions to position them at substantial angles to said four-ply layer, thereby producing a composite strip having a four-ply rib with flanges projecting laterally from opposite sides of the base of said rib, the remaining portion of said lower strip overlying one of said flanges and ex-

tending a substantial distance beyond the edge thereof to provide a wide reinforcement for the insole.

11. A machine for making ribbed strips for attachment to insoles to provide sewing ribs thereon having, in combination, mechanism for feeding a pair of strips in superimposed relation to each other and at equal speeds, a member for folding the upper strip upon itself during the feeding movement to form a two-ply layer, a guide for positioning the two-ply layer upon the lower strip, means for progressively folding the lower strip around a portion of said two-ply layer to cover both sides thereof and form a four-ply layer with the remaining portions of said two-ply layer and lower strip projecting therefrom, and stationary means for bending the plies of said remaining portion of the two-ply layer progressively in opposite directions to form flanges on said four-ply layer with the remaining portion of said lower strip underlying one of said flanges and extending a substantial distance beyond said flange, said stationary means also acting progressively during the bending operation to turn the combined strips bodily into a position in which the four-ply layer extends downwardly and the flanges project laterally from the opposite sides of said four-ply layer and substantially at right angles thereto.

12. A machine for making ribbed strips for attachment to insoles to provide sewing ribs thereon having, in combination, mechanism for feeding a pair of strips in unison, a member for folding one of said strips progressively during the feeding movement to form a two-ply layer, means for folding the other strip progressively around the two-ply layer to cover a portion thereof and form a four-ply layer, the remaining portions of said two-ply layer and other strip projecting beyond said four-ply layer, said folding means being also arranged to bend the plies of said remaining portion of the two-ply layer progressively in opposite directions to position them substantially at right angles to said four-ply layer to form lateral flanges thereon, thereby producing a composite strip having a four-ply rib with inner and outer flanges projecting laterally from the base thereof, and means for applying pressure progressively to the composite strip to compress the rib and also to press said inner flange and said rib together to cause the rib to incline toward said inner flange when the pressure is relieved.

13. A machine for making ribbed strips for attachment to insoles to provide sewing ribs thereon having, in combination, mechanism for feeding a pair of strips of indefinite length, a fixed member for folding one of said strips upon itself during the feeding movement to form a two-ply layer, stationary means for folding the other strip around the two-ply layer to cover a portion thereof and form a four-ply layer, the remaining portions of said two-ply layer and other strip extending from one end of the four-ply layer, means for bending the plies of said remaining portions of the two-ply layer in opposite directions during the feeding movement to position said plies substantially at right angles to the four-ply layer and thereby produce a composite strip having a four-ply rib with inner and outer flanges projecting laterally from opposite sides thereof, the remaining portion of said other layer overlying the inner flange and extending a substantial distance beyond said flange, and rolls constructed and arranged to

apply pressure progressively to the composite strip to press the rib and inner flange together in a plane substantially parallel to the plane of the outer flange to cause the rib to be inclined toward said inner flange when the pressure is relieved.

14. A machine for making ribbed strips for attachment to insoles to provide sewing ribs thereon having, in combination, mechanism for feeding strips of indefinite length in unison, means for folding said strips progressively during their feeding movement to form a composite strip having a multi-ply rib with flanges projecting laterally from opposite sides of the rib, and means for

15 applying pressure progressively to the upper portion of the rib to crimp said upper portion and produce a relatively narrow edge along the upper portion of the rib.

16. A machine for making ribbed strips for attachment to insoles to provide sewing ribs thereon having, in combination, mechanism for feeding a pair of strips of indefinite length in a pre-determined path, a member for folding one of said strips progressively during the feeding move-

20 ment to form a two-ply layer, means for folding the other strip around said two-ply layer to cover a portion thereof and form a four-ply layer with the remaining portions of said two-ply layer and other strip projecting therefrom, said four-ply layer forming a rib in the completed strip, and rolls for applying pressure progressively to said rib to compress the upper portion thereof and produce a relatively narrow edge along the upper portion of the rib in the finished strip.

30 17. A machine for making ribbed strips for attachment to insoles to provide sewing ribs thereon having, in combination, mechanism for feeding a pair of superimposed strips in unison, a member for folding one of said strips during the feeding movement to form a two-ply layer, means for progressively folding the other strip around said two-ply layer to cover a portion thereof and form a four-ply layer with the remaining portions of the two-ply layer and other strip pro-

40 jecting from one end thereof, mechanism for inserting fastenings through the four-ply layer, and means for bending said remaining portions of the two-ply layer and other strip at substantial angles relatively to said four-ply layer to 45 produce a composite strip having a four-ply rib with flanges extending laterally from the base thereof.

50 18. A machine for making ribbed strips for attachment to insoles to provide sewing ribs thereon having, in combination, mechanism for feeding a pair of strips in unison, a member for folding one of said strips during the feeding movement to form a two-ply layer, means for folding the other strip progressively around said two-ply layer to cover a portion thereof and form a four-ply layer with the remaining portions of the two-ply layer and said other strip projecting from one end thereof, mechanism for inserting stitches through the four-ply layer, and stationary means

60 for progressively bending the plies of the projecting portion of the two-ply layer in opposite directions to position them at substantial angles relatively to said four-ply layer, thereby producing a composite ribbed strip having a four-ply 65 rib with inner and outer flanges projecting laterally from opposite sides of the rib.

70 19. A machine for making ribbed strips for attachment to insoles to provide sewing ribs thereon having, in combination, intermittently operating mechanism for feeding a pair of superimposed

strips of indefinite length in unison, a fixed member for folding the upper strip upon itself during the feeding movement to form a two-ply layer, a guide for positioning said two-ply layer relatively to the lower strip, means for progressively folding said lower strip around said two-ply layer to cover a portion thereof and form a four-ply layer, the remaining portions of said two-ply layer and lower strip projecting from one end of said four-ply layer, means for inserting stitches through the four-ply layer adjacent to the end from which said remaining portions project, and means for progressively bending the plies of the remaining portion of said two-ply layer in opposite directions to position said plies at substantial angles to said four-ply layer to produce a composite strip having a four-ply rib with inner and outer flanges extending laterally from opposite sides of the rib, the remaining portion of said lower strip overlying the inner flange and extending a substantial distance beyond said flange to provide a wide reinforcement for the insole.

19. A machine for making ribbed strips for attachment to insoles to provide sewing ribs thereon having, in combination, mechanism for feeding in substantially parallel relation a pair of superimposed strips each having pressure-responsive cement on at least one surface thereof with the cemented surfaces facing in the same direction, a member for folding the cemented surface of one of said strips upon itself to form a two-ply layer, means for folding the cemented surface of the other strip around said two-ply layer to cover a portion thereof, the remaining portions of said two-ply layer and other strip projecting from the covered portion, means for applying pressure progressively to said covered portion to cause the plies to adhere to each other by reason of the cement thereon to form a four-ply layer, and means for bending the plies of said remaining portion of the two-ply layer in opposite directions during the feeding movement to position said plies at substantial angles to said four-ply layer, thereby producing a composite strip having an upstanding four-ply rib with flanges extending in opposite directions from the base of said rib, the bottom surfaces of said flanges being coated with pressure-responsive cement to adapt them for attachment to an insole by pressure alone.

20. A machine for making ribbed strips for attachment to insoles to provide sewing ribs thereon having, in combination, mechanism for feeding in superimposed relation a pair of strips having pressure-responsive cement on their upper surfaces, a member for folding the cemented surface of the upper strip upon itself during the feeding movement to form a two-ply layer, stationary means for folding the cemented surface of the lower strip progressively around said two-ply layer to cover a portion thereof and form a four-ply layer, the remaining portions of said two-ply layer and lower strip projecting beyond said four-ply layer, means for applying pressure progressively to the four-ply layer during the feeding movement to cause the plies to adhere together by reason of the cement thereon, and means for progressively bending the plies of said remaining portion of the two-ply layer in opposite directions to position them at substantial angles to said four-ply layer, thereby producing a composite strip having a four-ply rib with flanges projecting laterally from opposite sides of the base of said rib, one of said flanges being covered by the remaining portion of said lower strip which ex-

tends a substantial distance beyond the flange to provide a wide reinforcement for the insole.

21. A machine for making ribbed strips for attachment to insoles to provide sewing ribs thereon having, in combination, intermittently operating mechanism for feeding a pair of strips in substantially parallel relation to each other with at least one surface of each strip coated with pressure-responsive cement and with the cemented surfaces facing in the same direction, a member for folding the cemented surface of one of said strips upon itself during the feeding movement to form a two-ply layer, means for progressively folding the cemented surface of the other strip around said two-ply layer to cover a portion thereof and provide a four-ply layer for forming a rib, the remaining portions of said two-ply layer and other strip projecting beyond one end of said rib, a roll for applying pressure progressively to said rib to cause the plies thereof to adhere to each other, means for inserting stitches through the four-ply rib adjacent to one end thereof, and means for progressively bending the plies of the projecting portion of said two-ply layer in opposite directions to position them substantially at right angles to the four-ply rib and form inner and outer flanges thereon, the projecting portion of said other strip overlying the inner flange and extending a substantial distance beyond said flange, and the bottom surfaces of said flanges and said other strip having pressure-responsive cement thereon, thereby adapting the ribbed strip for attachment to a cement-coated insole by pressure alone.

22. A machine for making ribbed strips for attachment to insoles to provide sewing ribs thereon having, in combination, mechanism for feeding a pair of strips of indefinite length, a member for folding one of said strips progressively during the feeding movement, a guide for positioning the strips, a roll for pressing the folded strip after it has been folded, a stationary folder for progressively folding the other strip around a portion of the folded strip, a roll for pressing the folded portions of the two strips together, mechanism for inserting stitches through said folded portions, means for bending portions of the strips which extend beyond the folded portions into substantial angles relatively to said folded portions during said feeding movement, and a pair of rolls for applying additional pressure to the strips to complete the formation of the ribbed strip.

23. A machine for making ribbed strips for attachment to insoles to provide sewing ribs thereon having, in combination, mechanism for drawing a pair of strips of indefinite length from a source of supply, a fixed member for folding one of said strips upon itself during said movement to form a two-ply layer, a guide for positioning the two-ply layer relatively to the other strip, a stationary folder for folding said other strip progressively around said two-ply layer to enclose a portion thereof and produce a four-ply rib from one end of which remaining portions of said two-ply layer and other strip project, a roll for applying pressure to said four-ply rib, stitching mechanism for inserting stitches through said rib adjacent to said remaining portions, said stationary folder acting after the stitching operation to bend the plies of the remaining portion of said two-ply layer progressively in opposite directions to position them substantially at right angles to the four-ply rib and thereby form inner and outer flanges thereon, the inner flange being

covered by the remaining portion of said other layer which extends a substantial distance beyond said inner flange, and a pair of rolls for pressing the rib and inner flange together in a plane substantially parallel to the plane of the outer flange to cause the rib to incline inwardly toward said inner flange when the pressure is relieved.

24. A machine for making ribbed strips for attachment to insoles to provide sewing ribs thereon having, in combination, mechanism for feeding strips of indefinite length, means for operating upon said strips during their feeding movement to form a composite ribbed strip, mechanism for inserting a thread to form stitches through the strip, and means for automatically stopping the machine if the thread breaks.

25. A machine for making ribbed strips for attachment to insoles to provide sewing ribs thereon having, in combination, mechanism for feeding a pair of strips of indefinite length in unison, means for folding the strips during their feeding movement to form a composite ribbed strip, mechanism for inserting a thread progressively through the rib of the strip to form stitches therein, and means controlled by the tension of the thread for automatically stopping the machine if the thread breaks.

26. A machine for making ribbed strips for attachment to insoles to provide sewing ribs thereon having, in combination, mechanism for feeding a pair of strips in unison, means for operating progressively upon said strips during their feeding movement to form a composite strip having a multi-ply rib and a base, mechanism for inserting a thread to form stitches through said rib, power-operated means for actuating the feeding mechanism, operating means and stitching mechanism, a micro-switch, and means controlled by said thread for opening the micro-switch if the thread breaks and thereby automatically shutting off said power-operated means.

27. A machine for making ribbed strips for attachment to insoles to provide sewing ribs thereon having, in combination, means for supplying a pair of strips of indefinite length, mechanism for drawing the strips progressively from the supplying means, a member for folding one of the strips during their movement to form a two-ply layer, and means for progressively folding the other strip around said two-ply layer to cover a portion thereof and form a four-ply layer from which the remaining portions of the two-ply layer and other strip project, said folding means acting also during movement of the strips to bend said remaining portions of the two-ply layer and other strip into laterally extending positions relatively to the four-ply layer to produce a composite strip having a four-ply rib with flanges projecting laterally from the base of said rib.

28. A machine for making ribbed strips for attachment to insoles to provide sewing ribs thereon having, in combination, means for supplying in substantially untensioned condition a pair of strips of indefinite length each having pressure-responsive cement on at least one surface thereof, with the cemented surfaces facing in the same direction, mechanism for drawing the strips progressively from the supplying means, a member for folding the cemented surface of one strip upon itself during said movement to form a two-ply layer, means for folding the cemented surface of the other strip progressively around said two-ply layer to enclose a portion thereof and form a four-ply layer with remaining portions of the two-ply layer and other strip pro-

jecting therefrom, and means for bending the plies of the remaining portion of said two-ply layer in opposite directions during the feeding movement to position said plies at substantial angles to said four-ply layer and thereby produce a composite strip having a four-ply rib with flanges projecting laterally from opposite sides of the rib, one of said flanges being covered by the remaining portion of said other strip.

10 29. A machine for making ribbed strips for attachment to insoles to provide sewing ribs thereon having, in combination, means for supplying a pair of strips of indefinite length in parallel relation to each other, each of said strips having 15 pressure-responsive cement on at least one surface thereof, mechanism for feeding the strips in unison, means for withdrawing the strips from the supplying means in lengths sufficient to provide said feeding mechanism with the strips in a substantially untensioned condition irrespective of the rate of feed of said feeding mechanism, a member for folding a cemented surface of one of said strips over upon itself during the feeding movement to form a two-ply layer, means for 20 folding a cemented surface of the other strip progressively around said two-ply layer to cover a portion thereof and form a four-ply layer with the remaining portions of said two-ply layer and other strip projecting therefrom, mechanism for 25 inserting stitches through said four-ply layer, and means for bending the plies of said remaining portion to the two-ply layer progressively in opposite directions to position said plies at substantial angles to said four-ply layer, thereby producing 30 a composite strip having a four-ply rib with flanges projecting laterally from opposite sides of the base of the rib.

35 30. A machine for making ribbed strips for attachment to insoles to provide sewing ribs thereon 40 having, in combination, mechanism for feeding a pair of strips in unison, a member for folding one of said strips during the feeding movement to form a two-ply layer, means for progressively folding the other strip around a portion of the 45 two-ply layer to cover said portion and form a four-ply layer with the remaining portions of said two-ply layer and other strip extending therefrom, said folding means being also arranged during the feeding movement to bend the remaining portions of said two-ply layer and other strip progressively into lateral positions relatively to said four-ply layer to form flanges thereon, thereby producing a composite strip having a four-ply rib with flanges projecting laterally from the base of said rib, means for applying pressure 50 progressively to the composite strip to flatten said strip, and means for winding the strip upon a reel as it leaves the pressure applying means.

60 31. A machine for making ribbed strips for attachment to insoles to provide sewing ribs thereon having, in combination, mechanism for feeding a plurality of strips of indefinite length in unison, a member for folding one of said strips during 65 the feeding movement to form a two-ply layer, means for progressively folding another strip around a portion of said two-ply layer to cover said portion and form a four-ply layer with the remaining portions of the two-ply layer and said other strip projecting therefrom, said folding means being also arranged to bend said remaining portions laterally relatively to said four-ply layer to form flanges thereon, thereby producing 70 a composite strip having a four-ply rib with flanges projecting laterally from the base of said

75

rib, and means for automatically winding the composite ribbed strip upon a reel.

32. A machine for making ribbed strips for attachment to insoles to provide sewing ribs thereon having, in combination, mechanism for feeding a pair of strips in unison, a member for holding one of said strips during the feeding movement to form a two-ply layer, means for progressively folding the other strip around the two-ply layer to cover a portion thereof and form a four-ply layer with the remaining portions of said two-ply layer and other strip extending from one end of the four-ply layer, said folding means being also arranged during the feeding movement to bend the plies of the remaining portions of said two-ply layer in opposite directions to position them at substantial angles to said four-ply layer, thereby producing a composite strip having a four-ply rib with flanges projecting laterally from opposite sides of the rib, one of said flanges being covered by the remaining portion of said other layer which extends a substantial distance beyond said flange to provide a wide reinforcement for the insole, rolls for applying pressure progressively to the ribbed strip to force the rib and one of said flanges into a plane substantially parallel to the plane of the other flange, thereby temporarily flattening the ribbed strip, and means for automatically winding the strip upon a reel after it leaves said rolls.

33. A machine for making ribbed strips for attachment to insoles to provide sewing ribs thereon having, in combination, means for supplying a pair of strips of indefinite length, mechanism for drawing the strips progressively from the supplying means, a member for folding one of the strips during said movement to form a two-ply layer, means for progressively folding the other strip around said two-ply layer to enclose a portion thereof and form a four-ply layer with the remaining portions of said two-ply layer and other strip projecting beyond one end thereof, said folding means also acting during movement of the strips to bend said remaining portions into substantial angles relatively to the four-ply layer, thereby producing a composite strip having a multi-ply rib with flanges projecting laterally from the base of said rib, means for pressing the rib and flanges into substantially parallel planes thereby flattening the strip, and means for winding the flattened strip progressively upon a reel as it leaves said pressing means.

34. A machine for making ribbed strips adapted for attachment to insoles to provide sewing ribs thereon having, in combination, means for supplying a pair of strips of indefinite length in substantially untensioned condition, each of said strips having pressure-responsive cement on one surface thereof with the cemented surfaces facing in the same direction, mechanism for drawing the strips progressively from the supplying means, means for folding the strips during the feeding movement to form a composite strip having a four-ply rib with inner and outer flanges projecting laterally from opposite sides of the rib, rolls for pressing the ribbed strip temporarily into a relatively flat condition, and means for drawing the strip progressively from said rolls and winding it automatically upon a reel.

35. A machine for making ribbed strips adapted for attachment to insoles to provide sewing ribs thereon having, in combination, mechanism for feeding a pair of strips of indefinite length in unison, each strip having pressure-responsive

cement on at least one surface thereof, means for supplying the strips to said feeding mechanism in a substantially untensioned condition, said means being constructed and arranged to provide the strips in sufficient lengths to supply said feeding mechanism irrespective of its rate of feed, means for folding the cemented strips during the feeding movement to form a four-ply rib with inner and outer flanges thereon, said inner flange being covered by a layer which extends a substantial distance beyond said flange, a pair of rolls for progressively pressing the strip to flatten the rib against said inner flange, and power-operated means for drawing the flattened strip progressively from said rolls and winding it automatically upon a reel under sufficient tension to remain on said reel, said power-operated means being constructed and arranged to cease operating automatically when the reel is full.

36. A machine for making ribbed strips for attachment to insoles to provide sewing ribs thereon having, in combination, means for operating upon strips to form a composite ribbed strip, mechanism for feeding the strips past said operating means, and means for delivering the strips to said feeding mechanism in sufficient lengths to supply said mechanism irrespective of its rate of feed.

37. A machine for making ribbed strips for attachment to insoles to provide sewing ribs thereon having, in combination, means for operating upon strips to form a composite ribbed strip, mechanism for feeding the strips progressively past said operating means, and intermittently operating means for supplying a strip to said feeding mechanism constructed and arranged to provide the strip in sufficient lengths to supply the feeding mechanism irrespective of its rate of feed.

38. A machine for making ribbed strips for attachment to insoles to provide sewing ribs thereon having, in combination, means for operating upon strips to form a composite ribbed strip, mechanism for feeding the strips in unison past said operating means, and means for supplying a length of strip to said feeding mechanism which is equal to the length of strip that was fed by the preceding feeding movement.

39. A machine for making ribbed strips for attachment to insoles to provide sewing ribs thereon having, in combination, means for operating upon strips to form a composite ribbed strip, mechanism for feeding the strips progressively past said operating means, and means supplying a strip to said feeding mechanism in a substantially untensioned condition.

40. A machine for making ribbed strips for attachment to insoles to provide sewing ribs thereon having, in combination, means for operating upon strips to form a composite ribbed strip, mechanism for feeding the strips progressively past said operating means, and means for drawing one of the strips from a source of supply to deliver it to the feeding mechanism in a substantially untensioned condition, said last-named means being constructed and arranged to draw a sufficient length of strip from said source to supply the feeding mechanism irrespective of the speed of its feeding movement.

41. A machine for making ribbed strips for attachment to insoles to provide sewing ribs thereon having, in combination, means for operating upon strips to form a composite ribbed strip, some of said strips being coated with adhesive, reels for holding the strips, mechanism for feed-

ing the strips progressively past the operating means, and constantly operating means for withdrawing a coated strip from its reel to deliver it to the feeding mechanism in a substantially untensioned condition, said last-named means operating to provide said strip in sufficient lengths to supply the feeding mechanism irrespective of the speed of said feeding mechanism.

42. A machine for making ribbed strips for attachment to insoles to provide sewing ribs thereon having, in combination, means for operating upon strips of indefinite length to form a composite ribbed strip, mechanism for feeding the strips in unison past said operating means, and means for drawing a strip from a source of supply for delivery to the feeding mechanism substantially free of tension, said last-named means being constructed and arranged to draw a length of strip intermittently from said source of supply equal to the length of the feeding movement which precedes each operation of said means irrespective of the length of said feeding movement.

43. A machine for making ribbed strips for attachment to insoles to provide sewing ribs thereon having, in combination, means for operating upon strips of indefinite length to form a composite ribbed strip, mechanism for feeding the strips in unison past said operating means, constantly operating means for drawing lengths of one of said strips from a source of supply to deliver said lengths to said feeding mechanism substantially free of tension, and means for preventing the lengths of strip drawn from the source of supply from moving rearwardly toward said source of supply.

44. A machine for making ribbed strips for attachment to insoles to provide sewing ribs thereon having, in combination, means for operating upon strips of indefinite length to form a composite ribbed strip, mechanism for feeding the strips progressively past said operating means, spaced members over which one of said strips passes in a relatively taut condition, means for preventing reverse movement of the strip over said spaced members rearwardly toward a source of supply but permitting movement of the strip in the opposite direction, and rotatable eccentric means between said spaced members arranged upon each rotation to engage the strip and form a bend therein, thereby providing a length of strip for delivery to said feeding mechanism substantially free of tension.

45. A machine for making ribbed strips for attachment to insoles to provide sewing ribs thereon having, in combination, means for operating upon strips of indefinite length to form a composite ribbed strip, mechanism for feeding the strips progressively past said operating means, spaced rolls over which one of said strips passes from a source of supply in a substantially straight condition, means for presenting reverse movement of the strip over said rolls, and a crank constructed and arranged to rotate between said rolls and engage the strip intermittently during each rotation to pull a length of strip from the source of supply and form a bend between said rolls, thereby providing a length of strip under relatively light tension for delivery to said feeding mechanism.

46. A machine for making ribbed strips for attachment to insoles to provide sewing ribs thereon having, in combination, means for operating upon strips of indefinite length to form a composite ribbed strip, mechanism for feeding the

strips in unison past said operating means, spaced rolls over which one of said strips passes from a source of supply in a relatively straight condition, pawls for preventing reverse movement of the strip over said rolls, and eccentric means arranged to rotate between said rolls and engage the strip during each rotation to pull a length of strip from the source of supply and form a bend therein between said rolls, the length of strip pulled from the source of supply by said eccentric means being controlled by the amount of strip fed by said feeding mechanism prior to each rotation of the eccentric means.

47. A machine for making ribbed strips for attachment to insoles to provide sewing ribs thereon having, in combination, means for operating upon strips of indefinite length to form a composite ribbed strip, mechanism for feeding the strips progressively past the strip forming means, spaced rolls over which one of said strips passes from a source of supply to said forming means in a relatively taut condition, pawls associated with the rolls for engaging the strip and preventing retrograde movement thereof toward the source of supply but permitting movement of the strip toward said forming means, a crank rotatable between said rolls for engaging the strip intermittently and pulling off a length of strip from the source of supply to form a bend in the strip between said rolls, thereby providing excess strip for delivery to said feeding mechanism under relatively light tension, and means for releasing one of said pawls intermittently to vary the tension on the strip.

48. A machine for making ribbed strips for attachment to insoles to provide sewing ribs thereon having, in combination, means for operating upon strips of indefinite length to form a composite ribbed strip, mechanism for feeding the strips in unison past the forming means, spaced rolls over which one of the strips runs from a source of supply in a relatively taut condition, spring-pressed pawls associated with each roll for preventing reverse movement of the strip toward the source of supply but permitting movement thereof toward said forming means, a crank between said rolls rotatable to engage said strip intermittently and pull off a length from the source of supply to form a bend of excess strip between said rolls for delivery to said feeding mechanism under relatively light tension, and means actuated by said crank for removing one of said pawls from its roll intermittently during each rotation of the crank to vary the tension on the strip.

49. A machine for making ribbed strips for attachment to insoles to provide sewing ribs thereon having, in combination, means for operating upon strips of indefinite length to form a composite ribbed strip, mechanism for feeding the strips in unison past the forming means, means for drawing off a strip from a source of supply for delivery to the feeding mechanism substantially free of tension, and means for automatically stopping said last-named means before the strip is exhausted at the source of supply.

50. A machine for making ribbed strips for attachment to insoles to provide sewing ribs thereon having, in combination, means for operating upon a plurality of strips of indefinite length to form a composite ribbed strip, mechanism for feeding the strips in unison past said operating means, means for drawing one of said strips from a source of supply for delivery to the feeding mechanism substantially free of ten-

sion, and means for automatically stopping the operation of the machine before all of said strip has been drawn from the source of supply.

51. A machine for making ribbed strips for attachment to insoles to provide sewing ribs thereon having, in combination, means for operating upon a plurality of strips of indefinite length to form a composite ribbed strip, mechanism for feeding the strips in unison past the strip forming means, means for supplying the strips to the forming means and feeding mechanism substantially free of tension, power-operated means for operating said feeding means, and means for automatically stopping said power-operated means when the supply of strips on the supplying means becomes too low.

52. A machine for making ribbed strips for attachment to insoles to provide sewing ribs thereon having, in combination, means for operating upon strips of indefinite length to form a composite ribbed strip, mechanism for feeding the strips past the forming means, power-operated means for drawing off a strip from a source of supply to deliver it to the feeding mechanism substantially free of tension, and means controlled by the strip at the source of supply for stopping said power-operated means automatically when the strip at said source of supply has diminished a predetermined amount.

53. A machine for making ribbed strips for attachment to insoles to provide sewing ribs thereon having, in combination, means for operating upon cement-coated strips of indefinite length to form a composite ribbed strip, mechanism for feeding the strips progressively past the forming means, power-operated means for pulling a strip under substantial tension from a source of supply for delivery to the feeding mechanism under relatively light tension, and means for stopping the operation of said power-operated means automatically if the tension on said strip becomes so great that said means cannot pull the strip from said source of supply without danger of damaging the strip.

54. A machine for making ribbed strips for attachment to insoles to provide sewing ribs thereon having, in combination, means for operating upon strips of indefinite length to form a composite ribbed strip, mechanism for feeding the strips progressively past the forming means, power-operated means for pulling a strip under substantial tension from a source of supply for delivery to said feeding mechanism under relatively light tension, and means actuated by the strip for automatically stopping said power-operated means if the tension upon the strip becomes too great.

55. A machine for making ribbed strips for attachment to insoles to provide sewing ribs thereon having, in combination, means for operating upon cement-coated strips of indefinite length to form a composite ribbed strip, mechanism for feeding the strips in unison past the forming means, power-operated means for pulling a strip from a reel under substantial tension to provide a sufficient length of strip under relatively light tension to supply said feeding mechanism, means for stopping the power-operated means automatically before the strip on the reel is used up, and separate means for automatically stopping the power-operated means if the tension of the strip on the reel becomes so great that said power-operated means cannot pull the strip therefrom without danger of damaging the strip.

56. A machine for making ribbed strips for attachment to insoles to provide sewing ribs thereon having, in combination, means for operating upon strips of indefinite length to form a composite ribbed strip, mechanism for feeding the strips progressively past the forming means, reels for holding the strips, power-operated means for pulling a strip under substantial tension from its reel to supply said feeding mechanism, said power-operated means being constructed and arranged to deliver the strip to the feeding mechanism under relatively light tension, a micro-switch for controlling the operation of said power-operated means, a lever between the switch and said reel normally engaging the windings of strip on the reel, and means for holding said lever against said windings, said means causing the lever to open said switch automatically to stop said power-operated means when the windings of the strip upon the reel have diminished a predetermined amount.

57. A machine for making ribbed strips for attachment to insoles to provide sewing ribs thereon having, in combination, means for operating upon a pair of strips of indefinite length to form a composite ribbed strip, mechanism for feeding the strips progressively past the forming means, a reel for holding each strip, power-operated means for pulling one of said strips from its reel under substantial tension to supply said strip to the feeding mechanism under relatively light tension, said feeding mechanism drawing the other strip directly from its reel under light tension, a switch for controlling the operation of said power-operated means, and means for automatically opening the switch to stop said power-operated means when the supply of strip on either reel falls below a predetermined amount.

58. A machine for making ribbed strips for attachment to insoles to provide sewing ribs thereon having, in combination, means for operating upon a pair of cement-coated strips of indefinite length to form a composite ribbed strip, mechanism for feeding the strips progressively past the forming means, a reel for holding each strip, power-operated means for pulling one of said strips from its reel under substantial tension to supply said strip to the feeding mechanism under relatively light tension, said feeding mechanism drawing the other strip directly from its reel under relatively light tension, a switch for controlling the operation of said power-operated means, levers extending between said reels, and means urging one lever into engagement with the strip on one reel and urging the other lever into engagement with the strip on the other reel, either of said levers operating to open the switch automatically and stop said power-operated means when the windings of the strip on either reel fall below a predetermined amount.

59. A machine for making ribbed strips for attachment to insoles to provide sewing ribs thereon having, in combination, means for operating on a pair of strips of indefinite length to form a composite ribbed strip, mechanism for feeding the strips in unison past the forming means, a reel for each strip, continuously operating means for pulling one of said strips under substantial tension from its reel for delivery to said feeding mechanism under relatively light tension, the other strip being pulled directly from its reel by said feeding means, a micro-switch for controlling the operation of said continuously

operating means; means engaging the strips on both reels for opening the micro-switch automatically and stopping said continuously operating means when the strip on either reel falls below a predetermined amount, and means for opening said switch to stop said continuously operating means automatically if the tension on the strip being pulled from its reel by said continuously operating means should become great enough to damage the strip.

60. A machine for making ribbed strips for attachment to insoles to provide sewing ribs thereon having, in combination, means for operating upon strips of indefinite length to form a composite ribbed strip, mechanism for feeding the strips progressively past the strip forming means, means for pressing the ribbed strip into a relatively flat condition after it has been formed, and means for winding the strip automatically upon a reel after it leaves the pressing means.

61. A machine for making ribbed strips for attachment to insoles to provide sewing ribs thereon having, in combination, means for operating upon strips of indefinite length to form a composite ribbed strip, mechanism for feeding the strips in unison past the strip forming means, means for compressing the ribbed strip progressively during the feeding movement to put the strip into a relatively flat condition, power-operated means for winding the compressed strip upon a reel as it leaves the compressing means, and means for stopping said power-operated means automatically when the reel is full.

62. A machine for making ribbed strips for attachment to insoles to provide sewing ribs thereon having, in combination, means for operating upon strips of indefinite length to form a composite ribbed strip, mechanism for feeding the strips progressively past the forming means, a reel, power-operated means for operating the reel to wind the composite strip thereon after the strip has been formed, and means controlled by the strip on the reel for automatically stopping said power-operated means.

63. A machine for making ribbed strips for attachment to insoles to provide sewing ribs thereon having, in combination, means for operating upon strips of indefinite length to form a composite ribbed strip, mechanism for feeding the strips progressively past the forming means, a reel, and power-operated means for rotating the reel to wind the composite strip thereon after the strip has been formed, said power-operated means being constructed and arranged to cause the reel to exert a yielding tension continuously on the strip in winding it upon the reel.

64. A machine for making ribbed strips for attachment to insoles to provide sewing ribs thereon having, in combination, means for operating upon strips of indefinite length to form a composite ribbed strip, mechanism for feeding the strips at equal speeds past the forming means, a rotatable reel, power-operated means for rotating the reel to wind the composite strip thereon, and means for winding the strip substantially uniformly across the width of the reel.

65. A machine for making ribbed strips for attachment to insoles to provide sewing ribs thereon having, in combination, means for operating upon a pair of strips of indefinite length to form a composite ribbed strip, mechanism for feeding the strips in unison past the forming means, a reel, power-operated means for rotating the reel constructed and arranged to cause it to

draw the completed strip from said forming means under sufficient tension to wind the strip properly on the reel irrespective of the change in size of the reel due to the increasing windings thereon, and means for automatically distributing the strip substantially uniformly across the width of the reel.

66. A machine for making ribbed strips for attachment to insoles to provide sewing ribs thereon having, in combination, means for operating upon a pair of strips of indefinite length to form a composite ribbed strip, mechanism for feeding the strips progressively past the forming means, a reel, power-operated means including a clutch for rotating the reel, said means being constructed and arranged to draw the strip from the forming means under progressively less tension as the number of windings of the strip on the reel increases, means for automatically distributing the strip substantially uniformly across the width of the reel, and means controlled by the windings of the strip upon the reel for automatically stopping said power-operated means when said windings have reached a predetermined amount.

67. A machine for making ribbed strips for attachment to insoles to provide sewing ribs thereon having, in combination, means for operating upon strips of indefinite length to form a composite ribbed strip, mechanism for feeding the strips progressively past the forming means, a reel for receiving the composite strip, power-operated means including a friction clutch for normally rotating the reel at a uniform speed, said power-operated means being constructed and arranged to cause the reel to exert sufficient tension yieldingly on the strip to draw it from the forming means irrespective of the change in size of the reel due to the increased windings thereon, a lever for guiding the strip to the reel, and means for oscillating said lever to wind the strip substantially uniformly across the width of the reel.

68. A machine for making ribbed strips for attachment to insoles to provide sewing ribs thereon having, in combination, means for operating progressively upon strips of indefinite length to form a composite ribbed strip, mechanism for feeding the strips in unison past the forming means, a reel for receiving the completed strip, power-operated means for rotating said reel, a motor for actuating said feeding mechanism and said power-operated means, a microswitch controlling said motor, and means arranged to engage the windings of the strip upon the reel when the diameter of said windings reaches a predetermined size for opening the microswitch to shut off the motor and stop the operation of said feeding mechanism and power-operated means simultaneously.

69. A machine for making ribbed strips for attachment to insoles to provide sewing ribs thereon having, in combination, means for operating upon strips of indefinite length to form a composite ribbed strip, power-operated mechanism for feeding the strips progressively past the forming means, power-operated means for pulling one of said strips under substantial tension from a source of supply to deliver it to the feeding mechanism substantially free of tension, a reel for receiving the completed ribbed strip, power-operated means including a clutch for rotating the reel to wind the strip thereon, a motor for driving said power-operated means, a switch for controlling said motor, means actuated by the strip for automatically opening the

switch to stop both of said power-operated means simultaneously if the tension on the strip being pulled from said source of supply becomes too great, a second switch, and separate means actuated by the strip on the reel for opening the second switch to stop both of said power-operated means simultaneously when the windings of the strip on the reel reach a predetermined amount.

70. A machine for making ribbed strips for attachment to insoles to provide sewing ribs thereon having, in combination, means for operating upon strips of indefinite length to form composite ribbed strips for attachment to insoles, power-operated mechanism for feeding the strips progressively past the forming means, reels for supplying said strips, power-operated means for pulling one of said strips under substantial tension from its reel for delivery to the feeding mechanism under relatively light tension, a reel for receiving the ribbed strip after it has been formed, power-operated mechanism for rotating said reel to wind the strip upon the reel under relatively light tension, and means for automatically stopping the operation of the feeding mechanism, power-operated means and rotating mechanism simultaneously either when the strips on the supply reels have diminished a predetermined amount, or if the tension of the strip being pulled from its supply reel becomes great enough to damage the strip, or when the windings of the completed strip upon the receiving reel reach a predetermined amount.

71. A machine for making ribbed strips for attachment to insoles to provide sewing ribs thereon having, in combination, means for operating upon a pair of strips of indefinite length to form composite ribbed strips suitable for insoles, power-operated mechanism for feeding the strips in unison past the forming means, reels for supplying the strips, power-operated means for pulling one of said strips under substantial tension from its supply reel for delivery to the feeding mechanism under relatively light tension, a reel for receiving the ribbed strip after it has been formed, power-operated mechanism for rotating the receiving reel yieldingly to wind the completed strip thereon, a motor for driving said power-operated mechanism and said power-operated strip pulling means, means controlled by the strips on the supply reels for shutting off said motor automatically when the strip on either of said reels has diminished a predetermined amount, thereby stopping said power-operating mechanism and strip pulling means simultaneously, and means controlled by the diameter of the windings of the completed strip upon the receiving reel for automatically shutting off said motor when said diameter reaches a predetermined size, thereby simultaneously stopping said power-operated mechanism and said strip pulling means.

72. A machine for making ribbed strips for attachment to insoles to provide sewing ribs thereon having, in combination, mechanism for feeding strips of indefinite length in unison in a predetermined path, means for operating upon the strips progressively during their feeding movement to form a composite ribbed strip, mechanism for delivering the strips to the feeding mechanism substantially free of tension and in sufficient quantities to supply said feeding mechanism irrespective of its rate of feed, a reel, means for winding the ribbed strip upon the reel after it has been formed, means for actuating said

feeding and said delivering mechanisms and said operating and said winding means from a single source of power, and means for shutting off said power to stop the machine automatically if the supply of strips at the delivering mechanism falls below a predetermined amount, if the delivering mechanism becomes unable through tension on the strips to supply said strips, or when the reel upon which the ribbed strip is being wound has received a predetermined amount of the completed strip.

73. A machine for making ribbed strips for attachment to insoles to provide sewing ribs thereon having, in combination, mechanism for feeding a pair of strips of indefinite length in unison in a predetermined path, power-operated mechanism for delivering one of said strips to the feeding mechanism substantially free of tension and in sufficient quantity to supply said feeding mechanism irrespective of its rate of feed, said power-operated mechanism operating upon the strip when it is under substantial tension, means for winding the ribbed strip upon a receiving reel after it has been formed, said feeding mechanism, power-operated mechanism and winding means being actuated from a single source of power, and separate means associated with said power-operated mechanism and winding means for shutting off said power automatically to stop the machine if the supply of strips at the power-operated delivering mechanism falls below a predetermined minimum, if the delivering mechanism becomes unable through excessive tension on the strip to supply said strip to the feeding mechanism, or when the diameter of the reel receiving the completed strip reaches a predetermined size.

74. A machine for making ribbed strips for attachment to insoles to provide sewing ribs thereon having, in combination, mechanism for feeding a pair of strips in unison in a predetermined path, mechanism for delivering one of said strips to the feeding mechanism substantially free of tension in sufficient lengths to supply said feeding mechanism irrespective of its rate of feed, means for folding the strips progressively during their feeding movement to form a composite ribbed strip, mechanism for inserting a thread of stitches through the strip while it is being formed, means for winding the ribbed strip automatically upon a reel after it has been formed, power-operated means for actuating said folding and said winding means and said feeding, strip delivering and stitching mechanisms from a single source of power, and means for stopping the machine automatically if the supply of strips at the delivering mechanism becomes too low, if said delivering mechanism becomes unable through tension on the strip to supply said strip to the feeding mechanism, if the thread of the stitching mechanism breaks, or when the reel upon which the completed strip is being wound has received a predetermined amount of said strip.

75. That improvement in methods of making ribbed strips for attachment to insoles to provide sewing ribs thereon which comprises feeding strips of indefinite length in unison, folding one of said strips during the feeding movement to form a two-ply layer, folding another strip progressively around said two-ply layer to cover a portion thereof and form a four-ply layer with the remaining portions of said two-ply layer and other strip projecting therefrom, and bending said remaining portions of the two-ply layer and other strip at substantial angles to said four-

ply layer to produce a composite ribbed strip having a four-ply rib with flanges projecting laterally from the base of said rib.

76. That improvement in methods of making ribbed strips for attachment to insoles to provide sewing ribs thereon which comprises feeding a pair of strips of indefinite length in unison, folding one of said strips upon itself widthwise during the feeding movement to form a two-ply layer, moving the two-ply layer progressively into engagement with the other layer, folding said other layer progressively around the two-ply layer to cover a portion thereof and form a four-ply layer with the remaining portions of said two-ply layer and other strip projecting from one end of the four-ply layer, and bending the plies of said remaining portion of the two-ply layer in opposite directions relatively to the four-ply layer to produce a composite strip having a four-ply rib with flanges projecting from opposite sides of the rib, one of said flanges being covered by the remaining portion of said other layer to form a two-ply flange.

77. That improvement in methods of making ribbed strips for attachment to insoles to provide sewing ribs thereon which comprises feeding a pair of strips of indefinite length in a predetermined path, folding one of said strips widthwise upon itself during the feeding movement to form a two-ply layer while maintaining the other strip in a substantially flat position, guiding said two-ply layer into engagement with the flat strip intermediate of the opposite edges of said flat strip, folding the flat strip around said two-ply layer to cover a portion thereof and form a four-ply layer with the remaining portions of said two-ply layer and other strip projecting from one end thereof, and progressively bending the plies of the remaining portion of said two-ply layer in opposite directions laterally of the four-ply layer to position them at substantial angles to said four-ply layer, thereby forming a composite strip having a four-ply rib with flanges projecting laterally from opposite sides of the base of said rib, the remaining portion of said other strip overlying one of the flanges and extending a substantial distance beyond said flange to provide a wide reinforcement for the insole.

78. That improvement in methods of making ribbed strips for attachment to insoles to provide sewing ribs thereon which comprises feeding strips of indefinite length in unison in a predetermined path, folding one strip upon itself during the feeding movement to form a two-ply layer, guiding said two-ply layer into engagement with another strip, folding said other strip progressively around the two-ply layer to enclose a portion thereof and form a four-ply layer with the remaining portions of said two-ply layer and other strip projecting beyond said four-ply layer, applying pressure progressively to said four-ply layer to secure it in position, and bending the plies of said remaining portion of the two-ply layer in opposite directions to locate them at substantial angles to said four-ply layer and produce a composite ribbed strip having a four-ply rib with inner and outer flanges projecting laterally from the base thereof, said inner flange being covered by the remaining portion of said other strip to form a two-ply flange, said remaining portion extending a substantial distance beyond said inner flange to form a wide reinforcement for the insole.

79. That improvement in methods of making ribbed strips for attachment to insoles to pro-

vide sewing ribs thereon which comprises feeding a pair of strips in unison, folding one of said strips progressively during its feeding movement to form a two-ply layer while maintaining the other strip substantially flat, folding said other strip progressively around the two-ply layer to cover a portion thereof and form a four-ply layer with remaining portions of the two-ply layer projecting beyond its covered portion and with a margin of said other strip extending a substantial distance beyond said two-ply layer, bending the plies of the remaining portion of the two-ply layer in opposite directions to form lateral flanges at opposite sides of the four-ply layer with the extending margin of said other strip covering one of said flanges and extending a substantial distance beyond, and applying pressure progressively to the folded strips to bend the four-ply layer against the covered flange in a plane substantially parallel to the plane of the other flange, thereby temporarily flattening the four-ply layer against said covered flange.

80. That improvement in methods of making ribbed strips for attachment to insoles to provide sewing ribs thereon which comprises feeding a pair of strips of indefinite length in superimposed relation to each other, folding the upper strip upon itself during the feeding movement to form a two-ply layer, guiding said two-ply layer into engagement with the lower strip, folding said lower strip progressively around the two-ply layer to cover a portion thereof and form a four-ply layer with the remaining portion of the two-ply layer projecting therefrom and with one margin of the lower strip extending laterally a substantial distance beyond said remaining portion, bending the plies of the remaining portion of said two-ply layer progressively in opposite directions to locate them at substantial angles to the four-ply layer and thereby form a four-ply rib having inner and outer flanges projecting laterally from its base, one of said flanges being covered by the extending margin of said lower strip which extends a substantial distance beyond said flange, and applying pressure progressively to the composite ribbed strip to bend the rib temporarily against one of said flanges and thereby flatten the ribbed strip, said pressure being applied in a manner to compress the upper portion of the rib and thereby form a relatively narrow edge along the upper portion of the rib.

81. That improvement in methods of making ribbed strips for attachment to insoles to provide sewing ribs thereon which comprises feeding a pair of strips of indefinite length in unison, folding one of said strips during the feeding movement to form a two-ply layer, folding the other strip progressively around said two-ply layer to cover a portion thereof and form a four-ply layer with the remaining portion of the two-ply layer projecting therefrom and with one margin of said other strip projecting a substantial distance beyond said remaining portion, inserting stitches through the four-ply layer adjacent to the projecting portion of said two-ply layer, and bending the plies of the two-ply layer progressively in opposite directions to position them at substantial angles to said four-ply layer and thereby produce a composite strip having a four-ply rib with inner and outer flanges projecting laterally from the base of the rib, said inner flange being covered by the projecting margin of said other strip which extends a substantial distance beyond said flange.

75 82. That improvement in methods of making

ribbed strips for attachment to insoles to provide sewing ribs thereon which comprises providing strips of indefinite length at a source of supply, drawing the strips progressively from said source of supply, feeding the strips in unison in a predetermined path, operating upon the strips progressively during their feeding movement to form a composite strip having an upstanding rib with inner and outer flanges projecting laterally from the base of said rib, applying pressure progressively to the ribbed strip to compress the strip and flatten the rib temporarily against one of said flanges, and winding the strip upon a reel.

83. That improvement in methods of making ribbed strips for attachment to insoles to provide sewing ribs thereon which comprises providing strips of indefinite length at a source of supply, feeding the strips in unison from said source of supply in a predetermined path, operating progressively upon said strips during their feeding movement to form a composite strip having an upstanding rib with flanges projecting laterally from the base of said rib, applying pressure to the ribbed strip during said feeding movement to flatten the rib against one of said flanges, and winding the flattened strip automatically upon a reel.

84. That improvement in methods of making ribbed strips for attachment to insoles to provide sewing ribs thereon which comprises providing a pair of strips of indefinite length at a source of supply, drawing the strips progressively from the source of supply to provide strips under relatively light tension, feeding the strips in unison in a predetermined path, operating upon the strips progressively during their feeding movement to form them into a composite strip having an upstanding rib with inner and outer flanges projecting laterally from opposite sides of the base of said rib, applying pressure progressively to the strip by means of rolls to bend the rib downwardly against the inner flange and thereby temporarily flatten the ribbed strip, and winding the flattened strip upon a reel in a manner to distribute it substantially uniformly across the width of said reel.

85. That improvement in methods of making ribbed strips for attachment to insoles to provide sewing ribs thereon which comprises providing a pair of strips of indefinite length at a source of supply, one of said strips being coated with pressure-responsive cement on both sides and the other strip being coated with said cement on one side only, drawing the double-coated strip progressively from the source of supply to provide a length of said strip under relatively light tension, feeding the strips in superimposed parallel relation to each other with the cemented side of the single-coated strip facing the double-coated strip, folding the strips progressively while in this position in a manner to form a composite ribbed strip having a four-ply rib with flanges projecting lat-

erally from the opposite sides of the base of said rib, and applying pressure progressively to the ribbed strip to flatten it temporarily and thereby permit the strip to be readily wound upon a reel.

86. That improvement in methods of making ribbed strips for attachment to insoles to provide sewing ribs thereon which comprises feeding a pair of strips of indefinite length in unison, folding the strips progressively during the feeding movement to form a composite strip having an upstanding rib with flanges projecting laterally from opposite sides of the base of said rib, applying pressure progressively to the ribbed strip to bend the rib temporarily against one of said flanges and thereby flatten the strip, and winding the strip upon a reel while it is still in a flattened condition.

87. That improvement in methods of making ribbed strips for attachment to insoles which comprises providing a pair of strips of indefinite length at a source of supply, pulling one of said strips progressively from said source of supply to provide a length of said strip under relatively light tension, feeding the strips in superimposed relation to each other in a predetermined path, folding the strips progressively during their feeding movement to form a composite strip having four-ply, three-ply and single ply portions, inserting stitches through the four-ply portion adjacent to the three-ply portion, bending one ply of said three-ply portion in one direction laterally of the four-ply portion to position it substantially at right angles thereto, and bending the two remaining plies of said three-ply portion in an opposite direction laterally of the four-ply portion to position said plies at an acute angle to said four-ply portion, thereby forming a composite ribbed strip having a four-ply rib with a single ply flange at one side thereof and a two-ply flange at its opposite side with the rib inclining toward said two-ply flange.

Certificate of Correction

Patent No. 2,502,615

April 4, 1950

ALFRED S. CLARK

It is hereby certified that error appears in the printed specification of the above numbered patent requiring correction as follows:

Column 28, line 61, for the word "other", first occurrence, read *each*; column 35, line 7, for "holding" read *folding*; column 37, line 62, for "presenting" read *preventing*; column 43, lines 49, 55, and 61, for "mechanism" read *mechanisms*; and that the said Letters Patent should be read as corrected above, so that the same may conform to the record of the case in the Patent Office.

Signed and sealed this 14th day of November, A. D. 1950.
